ABSTRACT: A program-controlled semiautomatic metal casting process and apparatus involving a series of successive working and checking operations, including preliminary semiautomatic startup operations and final fully automatic melting, pouring, and shutdown operations. Commencement of each operation requires proper completion of the preceding operation. Certain of the operations proceed in accordance with a preselected casting program which may be varied, either by total program substitution or by manual adjustment of the individual program parameters, to provide the optimum program for the particular metal being poured and the particular shape being cast.

SEMIAUTOMATIC METAL CASTING APPARATUS

BACKGROUND OF THE INVENTION

1. Field of the Invention

This invention relates generally to the metal casting art. More particularly, the invention relates to a programmed, semiautomatic metal casting method and apparatus involving successive semiautomatic and fully automatic working and checking operations, certain of which proceed in accordance with a casting program which may be varied to provide the optimum program for the particular metal and shape being cast.

2. Prior Art

As will appear from the ensuing description, the present invention may be utilized for both atmospheric and vacuum casting applications. However, the invention is primarily concerned with and will be disposed in relation to vacuum casting.

Heretofore, vacuum casting of super alloys and other exotic metals has generally required manual control and manipulation of the casting apparatus. As a consequence, evaluation of the various steps of the casting process often vary from one operator to the next with the result that castings of uniform quality are difficult to obtain. Moreover, these manually controlled casting processes are excessively tedious and time consuming to practice owing to the numerous manual working and checking operations which the operator must perform properly, and in the proper sequence to obtain satisfactory casting. However, even with the utmost care on the part of the operator, errors and improperly performed casting operations often occur which result in substandard or totally unacceptable cast parts, as well as other adverse occurrences, such as excessive splash and hence loss of the metal being poured.

Another disadvantage of the existing manual casting techniques resides in the fact that many of the manual operations performed during the casting cycle are not subject to audit until completion of the cycle. Consequently, slight variations in the various operations introduced by different operators cannot be detected until the casting cycles are completed and then only by detection of variations in the cast parts. This method of detecting and correcting operator-induced variations in the casting process is very inefficient, at best, and relatively costly because of the nature of the equipment involved, the necessity of checking each casting, and the relatively high scrap rate.

SUMMARY OF THE INVENTION

According to one of its aspects, the invention provides a semiautomatic, precisely repeatable program controlled casting method and apparatus which avoid the above-noted and other disadvantages inherent in the existing manual casting techniques. To this end, the present casting method and apparatus involve a number of successive programmed working and checking operations, including initial semiautomatic startup operations and final fully automatic chamber pumpdown, melting, pouring, and shutdown operations. By way of example, a typical programmed casting cycle proceeds from initial conditioning of the casting apparatus for operation through loading of the metal charge into the crucible, evacuation of the vacuum chamber, checking of the chamber vacuum level, melting and superheating of the metal charge in the crucible, preheating of the crucible pouring lip, checking of the chamber vacuum level and the temperature of the molten charge, uncovering the preheated mold, pouring of the molten charge, venting of the vacuum chamber, shutdown of the apparatus, and final return of the apparatus to its initial state in readiness for the next casting cycle. Each step or operation of the casting cycle must occur to proper completion before the next operation can proceed. In some cases, this requires merely the performance of certain mechanical actions. In other cases, occurrence of an operation to proper completion requires expiration of a measured time delay. In yet other cases, proper completion of an operation necessitates the attainment of a predetermined temperature level or vacuum level.

Certain operations of the present casting process proceed in accordance with a preselected casting program which establishes the optimum casting parameters for the particular metal being cast, such as minimum chamber vacuum level, alloying temperature, and pouring temperature. The program also establishes other optimum parameters associated with the pouring operation including the optimum pouring angle and angular velocity profile of the crucible for the particular metal charge within the crucible to obtain accurate entrance of the molten stream into the mold with virtually no splash or contact of the molten metal with the rim of the mold.

According to one programming feature of the invention, the casting process is programmed with an information storage medium, such as a program card, which is coded to define a selected casting program. A number of these program cards, defining optimum casting programs for different metals and/or cast shapes may be prepared for selective insertion into the casting apparatus, depending upon the particular metal to be poured and the cast shape to be produced. According to another programming feature of the invention, the casting apparatus is provided with a substitute or manual programmer which permits manual adjustment or setting of the individual casting parameters during a test program, to produce any desired casting program. This manual programmer is useful in determining, by the experimental process of trial and error, an optimum casting program for a particular metal or shape to be cast. The apparatus may also be equipped with certain manual override switches to be selectively operated at any stage of the casting cycle to assume manual control of the cycle.

BRIEF DESCRIPTION OF THE DRAWINGS

In the drawings:

FIG. 1 is a diagrammatic illustration of the present casting apparatus;

FIG. 2 is a circuit diagram of the control panel of the apparatus;

FIGS. 3a, 3b, and 3c are circuit diagrams of the apparatus;

FIG. 4 illustrates a casting program card for use in the casting apparatus;

FIG. 5 is a perspective view of a card reader employed in the casting apparatus;

FIG. 5a is an enlarged section through contacts of the card reader;

FIG. 6 is a circuit diagram of the card reader;

FIG. 7 is a circuit diagram of the card reader timing circuit;

FIG. 8 is a circuit diagram of the crucible drive controller;

FIG. 9 is a circuit diagram of the vacuum system for the vacuum casting chamber;

FIG. 10 is a circuit diagram of the temperature monitor;

FIG. 11 is a circuit diagram of the heat controller;

FIG. 12 is a circuit diagram of the mold lid position controller; and

FIG. 13 is a circuit diagram of the manual programmer.

DESCRIPTION OF THE PREFERRED EMBODIMENTS

Reference is made first to FIG. 1 diagrammatically illustrating a semiautomatic metal casting apparatus 10 according to the invention. The casting apparatus includes a vacuum chamber 12 and vacuum pumping means 14 for evacuating the chamber. Exposed to the interior of the vacuum chamber is a vacuum level detector 16 for sensing the vacuum level within the chamber. At the bottom of the chamber is a mold 18 supported on a mold positioning table 20. A crucible 22, having an induction heating coil 23, is pivotally mounted over the mold and is coupled to a crucible tilt drive motor 25 for rotating the crucible through a range of angular positions. Associated with the mold 18 is a combination lid and positioning target 26 coupled to a lid operator 28. This operator may be actuated to move the mold lid between its broken and solid line positions of FIG. 1. The solid line position of the lid is its retracted position, wherein the lid is situated to permit pouring of metal from the crucible 22 into the mold 18. The

broken line position of the lid is its target position, wherein the lid closes the mold, which is preheated, to aid in retaining heat in the mold and serves as a target for positioning the mold 18 properly to receive molten metal from the crucible. At the top of the vacuum chamber 12, over and in a position to view the interior of the crucible 22, is an optical thermal sensor 30. Access to the interior of the vacuum chamber 12 to introduce, position, and remove the mold 18 and to load a metal charge into the crucible 22 is provided by a door 32. This door, when closed, hermetically seals the chamber.

Operation of the casting apparatus is controlled by a semiautomatic control system 34 powered from an electrical power supply 36. This control system includes a programmer 38 into which may be inserted an information storage medium containing a preselected casting program, and a substitute or manual programmer 40 which may be operated manually to adjust the individual casting cycle parameters, thus to preset into the control system any selected casting program. In the particular embodiment of the invention selected for presentation in this disclosure, the programmer 38 is designed to receive casting program cards which are prepared or coded to define different preselected casting programs. For this reason, the programmer 38 is hereinafter referred to as a card programmer. It will be understood, however, that other types of information storage media may be utilized to store the preselected casting programs. Also included in the control system is a program sequencer 42, a control panel 44, a crucible drive controller 45 for the crucible drive motor 25, a vacuum controller 46 for the vacuum pumping means 14, a heat controller 48 for the crucible heating coil 23, a mold lid position controller 50 for the lid operator 28, and a temperature monitor 52 for the thermal sensor 30. A master control circuit 54 interconnects the several components of the casting apparatus to accomplish the semiautomatic casting or pouring cycle of the invention. As noted earlier, this cycle involves a series of successive working and checking operations or steps, including preliminary semiautomatic startup operations and subsequently fully automatic melting, pouring, and shutdown operations. Certain of these operations proceed in accordance with the casting program stored in the card programmer 38 or preset into the manual programmer 40 in a manner such that the casting cycle occurs under the optimum conditions for the particular metal being poured and shape being cast.

A detailed description of the casting apparatus 10 will be presented shortly. In order to facilitate a full and complete understanding of the later description, however, it is advisable to discuss at this point an exemplary casting cycle in step-by-step sequence.

It will become evident from the later description, that the casting cycle is caused to proceed from one step to the next by stepping of the program sequencer 42. Each step of the cycle must occur to proper completion before the next step can occur. Accordingly, any malfunction during the casting cycle will automatically terminate the sequence until the malfunction is corrected. Moreover, as noted earlier and explained in detail later, manual control of the casting cycle may be assumed at any point in the cycle. In the ensuing discussion of the casting cycle, reference is made to various programmed functions or parameters, such as programmed crucible positions and tilt speeds, programmed time delays, programmed temperatures, programmed heating power levels, and so on. As will appear from the later description, these are parameters which are dictated or established by the selected casting program inserted into the card reader 38.

Attention is directed to the fact that the following steps define a typical casting program and are not to be construed as necessarily occurring in the order listed, as the order of sequence is versatile and changeable by simple resetting of the sequence order in the programmer sequencer 42. Moreover, the actual steps involved in the casting cycle may be varied by eliminating and/or adding steps.

PRECONDITION OF THE CASTING APPARATUS FOR AUTOMATIC CASTING OPERATION

Automatic operation of the casting apparatus 10 requires the execution of certain preliminary manual operations to condition the apparatus for its automatic casting cycle which are represented in this disclosure by actuation of automatic mode switches 56, 58 on the control panel 44. These actions energize the control system 54 and produce a stepping impulse which steps the program sequencer 42 from its initial or home position to initiate the first step of the casting cycle.

STEP 1

15 The first step of the typical casting cycle energizes the crucible drive motor 25 to rotate the crucible 22 to a programmed load angle and initiates an automatic checking operation which effectively checks the operational readiness of the heat controller 48 to supply heating power to the crucible heating coil 23. If the heat controller has been properly conditioned for operation during the initial precondition step, a stepping impulse is produced which steps the sequencer 42 to the second step of the casting cycle.

STEP 2

25 During this step of the casting cycle, bars or ingots of the metal to be cast are loaded into the crucible 22, and the mold lid operator 28 is actuated manually by button 59 on the changeable panel 44 to lower the mold lid 26 to its broken line target position of FIG. 1. In this regard, it should be noted that the mold lid is thus lowered only after the mold 18 has been placed in the vacuum chamber 12 and that the act of lowering the lid is utilized, in effect, as a control function to indicate the presence of the mold within the chamber. Arrival of the lid at its lower target position produces a stepping impulse for stepping the program sequencer 42 to the third step of the casting cycle.

STEP 3

35 In this step, the mold 18 is shifted manually into alignment with the currently lowered mold lid 26. When thus aligned, the mold is properly situated relative to the crucible 22 for pouring of molten metal from the crucible into the mold during a later pouring step of the casting cycle. The proper casting program card is then inserted into the card programmer 38 and the latter is closed. These actions produce a stepping impulse 40 which steps the program sequencer 42 to the fourth step of the casting cycle.

STEP 4

45 This step is the final manual step of the casting cycle and involves closing and locking of the vacuum chamber door 32 to hermetically seal the vacuum chamber 12. Closing of the door produces a stepping impulse which advances the program sequencer 42 to the fifth step of the casting cycle. The latter step constitutes the beginning of the fully automatic portion of the casting cycle during which the successive steps of the cycle occur automatically in sequence in response to proper completion of the preceding steps.

STEP 5

55 During this first automatic step of the casting cycle, the vacuum controller 46 and the heat controller 48 are energized to commence evacuation of the vacuum chamber 12 and condition the heat controller for the subsequent crucible heating step. The crucible drive controller 45 is activated to rotate the crucible 22 to a programmed melt position. Relation of the crucible to this position produces a stepping impulse for advancing the program sequencer 42 to the sixth step of the casting cycle.

STEP 6

This step activates the vacuum level detector 16 to check the vacuum level in the vacuum chamber 12. When this vacuum level reaches a programmed heat-start vacuum level, a stepping impulse is produced which advances the program sequencer 42 to the seventh step of the casting cycle.

STEP 7

In this step, the heat controller 48 is activated to energize the crucible heating coil 23 to programmed melt power level. Simultaneously, a programmed melt time delay is initiated and programmed superheat temperature information is fed to the temperature monitor 52. The programmed melt time delay represents the approximate heating time, less a selected fixed time interval such as one minute, required at the programmed melt power level to melt the metal charge within the crucible 22 and bring the molten metal to a temperature level which is less, by a preselected temperature difference, than the programmed superheat temperature. At the expiration of the melt time delay, a stepping impulse is produced to step the sequencer 42 to the eighth step of the casting cycle.

STEP 8

During this step, the crucible drive controller 45 is activated to rotate the crucible 22 at a relatively slow creep rate to an upright position in which the molten metal in the crucible is exposed to the thermal sensor 30. Also, control of the heat controller 48 is effectively transferred from the card programmer 38, which supplies the programmed melt power information for controlling the power level setting of the heat controller in step 7, to the temperature monitor 52. The temperature monitor activates the heat controller 48 to energize the crucible heating coil 23 at a preselected full controlled power level. Simultaneously, an additional fixed melt time delay, equal to the selected time delay interval referred to in step 7, i.e. 1 minute, is initiated. At the expiration of this fixed melt time delay, a stepping impulse is produced to advance the sequencer to its ninth step.

STEP 9

This step involves resumption of control of the heat controller 48 by the card programmer 38 and reduction of the power level setting of the heat controller to a programmed hold power level. After a short delay to permit thermal stabilization, the temperature monitor 52 is activated to compare the temperature of the molten metal with the programmed superheat temperature level and to determine the heating power level required to heat the metal to the superheat temperature. If the required heating power level is less than the programmed hold power level, a forward stepping impulse is produced which advances the program sequencer 42 to the following 10th step of the casting cycle. On the other hand, if the required power level is greater than the hold power level, a backstepping impulse is produced which returns the sequencer to the preceding eighth step of the casting cycle to repeat the latter step at controlled power level proportional to the temperature error. After expiration of the fixed heating time delay of the eighth step, the sequencer is again advanced to repeat the ninth step. This procedure is repeated, at a controlled heating power level which gradually drops as the metal temperature increases, until the heating power level required to achieve the programmed superheat temperature closely approaches the hold power level, indicating an acceptable temperature error, whereupon the sequencer advances to the 10th step.

STEP 10

In this step, the power level of the heat controller is reduced to a preset low level and the crucible drive controller 45 is activated to rotate the crucible 22 at the creep rate to a pro-

grammed lip heat position, wherein the molten metal within the crucible contacts but does not overflow the crucible pouring lip. Also, a programmed lip heat delay is initiated. This lip heat delay represents the time period required to heat the pouring lip at the power level to the proper pouring temperature and cool the molten metal from its superheat temperature to a temperature slightly above, i.e. on the order of 25° above, a programmed pouring temperature of the metal. A stepping impulse is produced at the expiration of the lip heat delay to advance the sequencer 42 to the 11th step of the casting cycle.

STEP 11

In this step, the crucible 22 is returned at the creep rate to its upright position and the heat controller 48 is activated by the temperature monitor 52 to energize the crucible heating coil at a controlled power level proportional to the temperature error between the metal temperature and the programmed pouring temperature. A fixed heating delay, such as 1 minute delay is initiated, after which a stepping impulse is produced to advance the sequencer 42 to the 12th step.

STEP 12

This step again activates the temperature monitor 52 to read the temperature of the molten metal within the crucible 22 after a brief delay to permit thermal stabilization and to compare the temperature of the molten metal with its programmed pouring temperature. If the temperature of the metal is less than its programmed pour temperature, a backstepping impulse is produced to return the sequencer 42 to its 11th step to repeat the latter step at a power level proportional to the temperature error. If the metal temperature exceeds the programmed pour temperature on the other hand, the system waits, applying heating power to the crucible at a preset minimum power level, until the metal temperature cools to the programmed pour temperature. When the exact pour temperature is attained, a stepping impulse is produced to advance the sequencer 42 to its 13th step.

STEP 13

This step returns the heat controller 48 to its programmed hold power level and verifies the existence of a programmed minimum pour vacuum level within the vacuum chamber 12. A stepping impulse is then produced to step the sequencer 42 to the following 14th step of the casting cycle.

STEP 14

During this step, the mold lid operator 28 is actuated by the mold lid position controller 50 to raise the mold lid 26 to its solid line retracted position of FIG. 1. The crucible drive controller 45 is actuated to rotate the crucible 22 to a final programmed pour angle at a programmed pour speed which is selected to cause entrance of the molten stream into the mold 18 with virtually no splash or contact of the molten metal with the rim of the mold. Rotation of the crucible to its final pouring position produces a stepping impulse for advancing the sequencer 42 to the final 15th step of the casting cycle.

STEP 15

This step is a cooling step during which all heating power to the crucible is turned off, and a programmed vent delay time is initiated. This vent delay time represents the time required for cooling of the poured metal under vacuum within the mold 18 to a selected reduced temperature. At the expiration of the delay, a stepping impulse is produced to advance the programmed sequencer 42 to its initial home position. Return of the sequencer to its home position cuts power to the vacuum and heat controllers 46, 48 to shutdown the vacuum pumping system 14 and automatically vent the vacuum chamber 12 to atmosphere and thereby complete the casting cycle.

The casting apparatus 10 of the invention which has been selected for illustration will now be described in greater detail

by initial reference to FIG. 3. In the ensuing description, programmed control information is referred to in terms which connote the functions to which the information relates. For example, programmed information relating to a crucible position is referred to as angle select information. Melt angle selection information, for instance, is programmed crucible position information which dictates the angular position in which the crucible 22 is to be located during the melt phase of the casting cycle. Programmed information relating to heating power level, temperatures, time delays, crucible tilt rate, etc., is referred to in similar terms. Pour temperature select information, for example, is control information which dictates a preselected temperature at which the molten metal is to be poured. As it will appear from the later description, this control information is electrical information in the form of voltage signals. In a similar manner, certain mechanical elements of the casting apparatus are referred to in terms which indicate the functions performed by the respective elements. By way of example, a melt angle select switch is referred to in the ensuing description. This is a switch for feeding melt angle select information from the card programmer 38 to the crucible drive controller 24. It will be understood, of course, that the various functions referred to in the description are those mentioned in the earlier discussion of the casting cycle.

Turning now to FIG. 3, the illustrated program sequencer 42 is a rotary stepping drum-type sequencer, such as that marketed by the Tenor Company of Milwaukee, Wis., under the name Tenor Programmer. This sequencer is diagrammatically illustrated in FIG. 3 as comprising a number of switches 60, a rotary drum 62 having changeable pins 63 for actuating the switching in a desired sequence as the drum rotates, and an electrical stepping actuator 64 for rotating the drum in step-wise fashion through a number of successive positions or steps. In this instance, the sequencer drum 62 uses 16 positions or steps corresponding to the initial conditioning step and 15 working steps of the casting cycle described earlier. Fewer or additional steps may be employed, depending upon the number of steps in the casting cycle.

In connection with actuation of the sequencer switches 60 by the sequencer drum 62, it will appear from the ensuing description that each switch has a normal position and a second position to which the switch is operated by the drum. In some cases, the drum may operate a switch in only one drum stepping position. In other cases, the drum may operate a switch in a number of stepping positions, either consecutive stepping positions or spaced stepping positions. The switch operating pins 63 on the drum may be so arranged that a switch which is operated in a number of consecutive stepping positions remains in its drum actuated position continuously throughout these positions including the intervals during which the drum steps from one position to the next. Attention is directed to the bracketed numerals below the broken lines representing the drum pins 63 in FIG. 3. These numerals identify the stepping position or positions of the drum in which the corresponding drum switch 60 is actuated.

Power supply 36 provides both AC and DC power for operating the casting apparatus in the manner explained in the ensuing description. In this regard, attention is directed to the fact that the casting apparatus and its operation are described below in relation to the typical or exemplary casting cycle discussed earlier. Accordingly, it should be understood that the invention contemplates within its scope various modifications, which will become obvious as the description proceeds, to accommodate variations in the casting cycle.

The stepping actuator 64 of program sequencer 42 has two stepping leads 68 and 70. Lead 68 is forward stepping lead, energizing of which advances the sequencer drum 62 one step in the forward direction. Lead 70 is a backstepping lead, energizing of which steps the drum back one step. At the start of each casting cycle of the casting apparatus 10, the sequencer 42 (i.e. the sequencer drum 62) occupies an initial position H, referred to herein as its home position. FIG. 3 illustrates this position. When in its home position, the sequencer closes two

normally open switches 72, 76 and opens a normally closed switch 74. Switch 72 is a load angle select switch. This switch, when closed, completes a circuit from a load angle select terminal of the card programmer 38 through a lead 80, the switch contacts, and a lead 82 to the crucible drive controller 45. As it will appear from the later description, this circuit is utilized to feed programmed load angle information to the drive controller for energizing the crucible drive motor 25 to rotate the crucible 22 to a programmed loading position. Sequencer switch 74 is a creep relay switch. This switch, when closed, completes an energizing circuit from a low voltage lead 83 of the power supply 36 through a lead 84, the switch contacts, and a lead 86 to the crucible controller 45 for energizing a creep relay within the controller. As explained later, the creep relay, when thus energized, conditions the drive controller to energize the crucible drive motor at a relative slow creep rate in response to angle select information, such as the load angle select information just mentioned, for rotating the crucible 22 at this rate to the position represented by the information. Programmer switch 76 is an automatic power-on check switch. This switch, and a set of normally open contacts 56a are connected in electrical series between the low voltage supply lead 83 and the sequencer forward stepping lead 68. Closure of the contacts 56a thus applies a forward stepping voltage to the program sequencer 42 which steps the latter from its home position H to its first stepping position. As will be explained presently, contacts 56a are contacts of the automatic mode switch 56 on the control panel 44 which are closed by actuation of the switch. Actuation of switch 58 energizes the control system including lead 83 from the power supply 36. Thus, actuation of both switches conditions the casting apparatus for its casting cycle and steps the sequencer from its home position to its first stepping position.

As indicated in FIG. 3, the load angle select switch 72 remains closed from the home position H through the fourth stepping position and is then reclosed from the 15th stepping position back to the home position H of the sequencer 42. Creep relay switch 74 is open in the home position of the sequencer and closes to energize the creep relay when the sequencer advances to its first stepping position. The switch reopens to deenergize the creep relay in the 13th and 14th stepping positions. The automatic power-on check switch 76 is closed only in the sequencer home position and opens when the sequencer steps from this position.

It is now evident that actuation of the switches 56, 58 in the home position of the sequencer 42 feeds programmed crucible load angle information from the card programmer 38 to the crucible drive controller 45, supplies operating power to the control system and closes the sequencer stepping contacts 56a to advance the program sequencer 42 to its first stepping position.

Stepping of the program sequencer 42 to its first stepping position closes the creep relay switch 74 to energize the creep relay in the crucible drive controller 45. The programmed crucible load angle information which is currently being fed to the controller through the closed sequencer load angle select switch 72 then actuates the controller to drive the crucible 22 at the creep rate to the programmed load angle. In its first stepping position, the sequencer 42 also closes a normally open MLC (main line contactor) check switch 90. Switch 90 and a set of normally open contacts 92a are connected in electrical series between the supply lead 83 and the sequencer forward stepping lead 68. Accordingly, closure of the contacts 92a applies a forward stepping voltage to the sequencer 42 which steps the latter from its first stepping position to its second stepping position. Contacts 92a are contacts of an MLC (main line contactor) relay embodied in the heat controller 48. As explained later, this relay is energized to close its contacts upon proper completion of the precondition steps at the outset of the casting cycle. Accordingly, if these precondition steps have been properly completed, closure of the MLC check switch 90 by the sequencer drum 62 upon stepping of the latter to its first position results in immediate stepping of

the drum to its second stepping position. The MLC check switch reopens upon stepping of the drum.

From the earlier description of the typical casting cycle, it will be recalled that in the second step of the cycle, the mold lid 26 is lowered to its broken line position of FIG. 3 to signify that the mold 18 has been placed in the vacuum chamber 12 and to permit use of the lid as a target for placement of the mold in proper pouring position relative to the crucible 22. Arrival of the lid in its lower target position closes a normally open lid-down limit switch 94 actuated by the mold lid operator. Switch 94, and a normally open switch 96 of the program sequencer 42 are connected in electrical series between the low voltage supply lead 83 and the sequencer forward stepping lead 68. Sequencer switch 96 is a lid-down check switch which is closed in the second stepping position of the sequencer. Thus, with the sequencer in its second stepping position, lowering of the mold lid 26 to its target position applies a forward stepping voltage to the sequencer which steps the latter to its third stepping position. The lid-down check switch 96 reopens when the sequencer steps.

In the third stepping position of the program sequencer 42, the card programmer 38 is opened and a previously prepared casting program card is inserted. In FIG. 3, the card programmer is diagrammatically illustrated as having a hinged cover 100 which may be rotated to open position for insertion of the program card. After the card has been properly inserted into the programmer, the latter is closed by rotation of its cover 100 to closed position. The card programmer 38 and the casting program card will be described in detail presently. Suffice it to say at this point that the card programmer embodies normally open switches 102, 103 which are closed by proper placement of a program card in the programmer and by closure of the programmer cover 100, respectively. These switches and a normally open switch 104 in the program sequencer 42 are connected in electrical series between the supply lead 83 and the sequencer forward stepping lead 68. Switch 104 is a normally open card programmer check switch which closes in response to stepping of the sequencer to its third stepping position. It is now evident, therefore, that insertion of a program card into the card programmer 38 and closure of the latter with the program sequencer 42 in its third stepping position applies a forward stepping voltage to the sequencer which steps the sequencer to its fourth stepping position.

Stepping of the sequencer 42 to its fourth stepping position closes a normally open vacuum chamber door check switch 106. Switch 106 and a switch 108 are connected in electrical series between the supply lead 83 and the sequencer forward stepping lead 68. Switch 108 is operated by the door 32 of the vacuum chamber 12 in such a way that the switch closes when the door is closed to seal the chamber. Thus, closure of the chamber door 32 during the fourth step of the casting cycle steps the program sequencer 42 to its fifth stepping position. In this regard, it is significant to recall that the first four steps of the casting cycle require manual operations for their completion. The remaining steps of the cycle, commencing with step number 5, are fully automatic.

Stepping of the sequencer 42 to its fifth stepping position closes a normally open switch 110 which is hereinafter referred to as a vacuum-heat controller switch. One terminal of this switch is connected to the low voltage power supply lead 83. The other terminal of the switch is connected through a lead 113 to the vacuum controller 46 and heat controller 48. Accordingly, closure of the vacuum-heat controller on switch 110 in stepping position 5 of the program sequencer 42 connects the vacuum and heat controllers to the supply lead 83. The vacuum and heat controllers will be described in detail presently. Suffice it to say at this point that connection of the controllers to the supply lead 83 activates the controllers. The vacuum controller 46, when thus activated, immediately energizes the vacuum pumping means 14 to commence evacuation or pump-down of the vacuum chamber 12. The heat controller 48, when activated, on the other hand, is merely condi-

tioned to energize the crucible heat coil 23. In this regard, it will be seen that the MLC contacts in the heat controller, which were closed at the start of the casting cycle, are reopened in response to activation of the heat controller at this point to open the energizing circuit between the controller and the heating coil. The MLC contacts are reclosed to energize the coil in the seventh step of the sequencer. It is significant to note here that the sequencer switch 110 remains closed, and hence the vacuum and heat controllers remain in their activated or on condition, from the fifth stepping position through the 15th stepping position of the program sequencer 42.

Stepping of the program sequencer 42 to its fifth stepping position also closed a pair of normally open switches 114 and 116. Switch 114 is a melt-angle select switch which completes a circuit from a melt-angle terminal of the card programmer 38, through a lead 118, the switch contacts, and a lead 120 to the lead 82 extending to the crucible drive controller 45. As will appear presently, this circuit is utilized to feed a programmed crucible melt-angle signal from the card programmer to the crucible drive controller. This signal activates the controller to energize the crucible drive motor 25 for rotating the crucible 22 at its creep rate from its current load-angle position to the programmed melt-angle position. The melt-angle select switch 114 remains closed, so that the crucible remains in its programmed melt-angle position, from the fifth stepping position through the seventh stepping position of the program sequencer 42.

Associated with the crucible drive system is a normally open switch 121 which is momentarily closed in response to rotation of the crucible 22 from its load angle position to its melt-angle position as well as in response to later rotation of the crucible to its pour-angle position. In the particular embodiment of the invention selected for illustration, the switch 121 closes in response to rotation of the crucible through an 80° position (i.e. a position displaced 80° from the horizontal and 10° from the vertical). For this reason, the switch 121 is referred to for convenience as an 80° switch. The 80° switch 121 and a fixed delay timer 122 are connected in electrical series to the supply lead 83 so that closure of the switch energizes the timer to commence running of a fixed delay time to be discussed presently. The timer has normally open contacts 122a in series with a sequencer switch 116 which closes in the fifth stepping position. At the expiration of its fixed delay, timer closes its contacts to connect lead 83 to the sequencer forward stepping lead 68. Closure of the 80° switch 121 in response to rotation of the crucible 22 through its 80° position with the sequencer in its fifth stepping position thus applies a forward stepping voltage to the sequencer for advancing the latter to its sixth stepping position.

As noted in FIG. 3 of the drawings, sequencer switch 116, hereinafter referred to as an 80° stepping switch, opens upon stepping of the sequencer and subsequently recloses in the 14th stepping position of the sequencer.

It is now evident, therefore, that stepping of the program sequencer 42 to its fifth stepping position turns on the vacuum controller 46 to commence pumpdown of the vacuum chamber 12 and turns on the heat controller 48 to condition the latter for energizing the crucible heating coil 23 in the seventh step of the sequencer. The crucible drive controller 45 is also activated to drive the crucible 22 from its programmed load-angle position to its programmed melt-angle position. Rotation of the crucible through its 80° position on its way to its melt-angle position advances the program sequencer 42 to its sixth stepping position.

In the sixth stepping position of the program sequencer 42, a normally open vacuum-step switch 124 is closed. This switch completes a stepping circuit from a vacuum-step terminal of the card programmer 38, through a lead 126 and the switch contacts to the sequencer forward stepping lead 68. As will appear from the later description, the chamber vacuum level detector 16 and the card programmer 38 cooperate to produce a stepping voltage at the latter programmer terminal

in response to reduction of the pressure within the vacuum chamber 12 to or below a programmed heat-start vacuum level. This stepping voltage is applied to the sequencer stepping lead 68 through the circuit 124, 126 to step the sequencer 42 to its seventh stepping position. In this regard, it is significant to recall that evacuation of the vacuum chamber 12 commences in the preceding stepping position of the sequencer 42 by closure of its vacuum-heat controller on switch 110.

From the foregoing discussion, it will be understood that in the sixth stepping position of the program sequencer 42, the vacuum chamber 12 is pumped down by the vacuum pumping means 14, thereby reducing the pressure within the chamber. When the vacuum chamber is finally evacuated at least to the programmed heat start vacuum level, the sequencer 42 is advanced to its seventh stepping position.

Stepping of the program sequencer 42 to its seventh stepping position closes a group of five normally open switches 130, 132, 134, 136, and 138. Switch 130 is a heating power-on switch which completes a circuit from the low voltage power supply lead 83 through the switch contacts and a lead 140 to the heat controller 148. As will appear from the later description, the voltage which is thus applied to the heat controller recloses the MLC contacts in the heat controller to energize the crucible heating coil 23. The switch 130 remains closed through the 14th stepping positions of the sequencer. Sequencer switch 132 is a melt power select switch. Closure of this switch completes a circuit from a melt power terminal of the card programmer 38 through a lead 142, the switch contacts, and a lead 144 to the heat controller 48. From the later description, it will be seen that a programmed melt power level signal is thereby fed from the card programmer 38 to the heat controller 48. This signal adjusts the controller to energize the crucible heating coil 23 at the programmed melt power level. Switch 132 opens in response to stepping of the sequencer 42 to its next stepping position. The third switch 134 to be closed in the seventh stepping position of the sequencer 42 is a superheat temperature select switch which remains closed through the ninth stepping position. Closure of this switch completes a circuit from a superheat temperature terminal of the card programmer 38, through a lead 146, the switch contacts, and a lead 148 to the temperature monitor 52. A programmed superheat temperature signal is thereby fed from the card programmer 38 to the monitor to be utilized in the manner explained below.

The two remaining switches 136 and 138 which close in the seventh stepping position of the program sequencer 42 are utilized to effect a timing function. Thus, switch 136 is a heating time delay start switch having one terminal connected to the power supply lead 83. The other terminal of the switch is connected through a lead 150 to a melt time delay power terminal of the card programmer 38. Closure of the switch 136 energizes a timing circuit embodied in the card programmer to commence running of a programmed melt time delay, as explained later. At the expiration of this delay, the timing circuit produces a stepping voltage at a melt time delay step terminal of the card programmer. This stepping voltage is applied to the sequencer stepping lead 68 through a lead 152 and the currently closed sequencer switch 138 to advance the sequencer to its eighth stepping position. This latter switch is hereinafter referred to as a time delay stepping switch. It will be noted that the melt time delay start switch 136 is closed only in the seventh stepping position of the sequencer 42, while the time delay stepping switch 138 is closed in stepping positions Nos. 7, 10, and 15.

From the foregoing description, it will be understood that the seventh stepping position of the program sequencer 42 energizes the crucible heating coil 23 to a programmed melt power level to commence melting of the metal within the crucible 22. Simultaneously, programmed superheat temperature information is fed to the temperature monitor 52 and a programmed melt time delay is started. The length of this delay is selected to equal the time duration, less a fixed time

interval of typically 1 minute duration, required to melt the metal charge in the crucible and heat the molten metal to a temperature on the order of 100° less than the programmed superheat temperature. At the expiration of the melt time delay, the sequencer 42 is advanced to its eighth stepping position.

In its eighth stepping position, the sequencer 42 closes a normally open switch 154. Closure of this switch completes a circuit from the power supply lead 83 through the switch contacts and a lead 156, to a fixed delay timer 158 having normally open contacts 158a. A voltage is thereby applied to the timer to commence running of a fixed time delay. At the expiration of this delay, which is equal to the fixed time interval, i.e. 1 minute, referred to in the preceding stepping position of the sequencer 42, the timer contacts 158a close. These timer contacts are connected in electrical series between the supply lead 83 and the sequencer stepping lead 68. Accordingly, closure of the timer contacts steps the sequencer 42 to its ninth stepping position. Lead 156 also extends to the temperature monitor 52. Accordingly, a voltage is applied to the monitor concurrently with energizing of the fixed delay timer 158. As will be explained presently, this voltage and the programmed superheat temperature signal which is currently being applied to the temperature monitor through the sequencer switch 134 cooperate to effect electrical connection of the temperature monitor to the heat controller 48 and actuation of the monitor to transmit a programmed heating power level signal from a full controlled power level terminal of the card programmer 38, through a lead 159a the temperature monitor, and a lead 159b to the heat controller. This power level signal, hereafter referred to as a full controlled power level signal, adjusts the heat controller to energize the crucible heating coil 23 at the programmed full controlled power level. As will appear from the later description, the above actuation of the temperature monitor 52 in response to closure of the sequencer switch 154 involves a controlled power level locking function in the monitor. For this reason, the switch is hereafter referred to as a controlled power level lock switch or simply a power lock switch.

In the eighth stepping position of the sequencer 42, then, the crucible heating coil 23 is energized at the programmed full controlled power level for a fixed period of time, in this instance 1 minute. The sequencer 42 then advances to its ninth stepping position. The power lock switch 154 reopens when the sequencer steps and subsequently recloses in the 11th sequencer stepping position. Reopening of switch 154 deenergizes the fixed delay timer 158, which then resets automatically in readiness for its next timing cycle, and disconnects the temperature monitor 52 from the heat controller 48 to terminate energizing of the heating coil 23 at the full controlled power level.

In its ninth stepping position, the program sequencer 42 closes a pair of normally open switches 160 and 162. Switch 160 is a hold power level select switch which reopens when the sequencer steps and subsequently recloses in the 13th and 14th stepping positions. Closure of this switch completes a circuit from a hold power level terminal of the card programmer 38, through a lead 164, the switch contacts, and a lead 166 and the lead 144 to the heat controller 48. As will be explained later, a programmed hold power level signal is thereby fed from the card programmer 38 to the heat controller 48. This signal adjusts the heat controller to energize the crucible heating coil 23 at the programmed hold power level which is selected to produce a crucible heating temperature approximating a programmed pouring temperature of the molten metal in the crucible. Sequencer switch 162 is a temperature interrogate switch which closes in the ninth stepping position only to complete a circuit from the power supply lead 83 through the switch contacts and a lead 168 to a fixed delay timer 170 having normally open contacts 170a. Accordingly, closure of the switch 162 energizes the timer to commence a fixed time delay. At the expiration of this delay, the timer contacts 170a close to connect the lead 168 to a lead 172 extend-

ing to the temperature monitor 52. As explained later, the voltage signal which is thus applied to the temperature monitor 52 effectively interrogates the monitor to determine the heating power level required to heat the molten metal in the crucible to its programmed superheat heat temperature. The fixed delay introduced by the timer 170 permits stabilization of the temperature monitoring system. Extending from the temperature monitor are leads 174 and 176. Lead 174 connects to the forward stepping lead 68 and lead 176 to the backstepping leads 70 of the program sequencer 42. As will also appear from the later description, the temperature monitor 52 responds to the incoming interrogate signal by applying a forward stepping voltage to the lead 174 if the required heating power level is less than the programmed hold power level and a backstepping voltage to the lead 176 if the required power level exceeds the hold power level.

It will now be understood that in the ninth stepping position of the sequencer 42, the temperature monitor 52 is interrogated concerning the heating power level required to heat the molten metal within the crucible 22 to its programmed superheat temperature. If the required heating power level change exceeds 50 percent of the programmed full controlled power level, the sequencer is returned to its eighth stepping position to repeat the 1-minute heating step of this position. As explained later, however, during this reheating step, the crucible heating coil 23 is energized at a controlled power level proportional to the temperature error between the programmed superheat temperature and the actual metal temperature. On the other hand, if the required heating power is less than 50 percent of the full controlled power level, the sequencer is advanced to its 10th stepping position.

In its 10th stepping position, the sequencer 42 closes three normally open switches 178, 180, and 182. Switch 178 is a lip heat angle select switch. Closure of this switch completes a circuit from a lip heat angle terminal of the programmer 38, through a lead 184, the switch contacts, lead 186 and the lead 82 to the crucible drive controller 24. From the later description, it will appear that this action feeds a programmed lip heat angle signal from the card programmer 38 to the crucible drive controller 24. The drive controller energizes the crucible drive motor 25 in response to this signal to rotate the crucible 22 at its slow creep rate to a programmed lip heat angle position. In this position, the molten metal within the crucible contacts but does not overflow the crucible pouring lip. Switch 180 is a lip heat delay start switch. Closure of this switch connects the power supply lead 83 to a lip heat delay power terminal of the card programmer 38 through the switch contacts and a lead 188. A voltage is thereby applied to the card programmer which activates the timing circuit in the programmer to generate a programmed lip heat delay time. This lip heat delay is selected to equal the time duration, less a fixed time interval such as 1 minute, required to heat the crucible pouring lip to the proper pouring temperature and cool the molten metal in the crucible from its current superheat temperature to a temperature slightly above, typically on the order of 25° F. above, a programmed pouring temperature. In this regard, it is significant to note that in the 10th stepping position, no heating power level signal is supplied to the heat controller 48. As will be seen later, under these conditions, the heat controller energizes the crucible heating coil 23 at a reduced power level which permits cooling of the metal as just stated. Switch 182 is a pour temperature select switch which remains closed through the 12th stepping position. Closure of this switch completes a circuit from a pour temperature terminal of the card programmer 38 through a lead 189, the switch contacts, a lead 190 and the lead 148 to the temperature monitor 52. Programmed pour temperature signal is then fed from the card programmer to the monitor to be utilized in the manner explained below.

At the expiration of the programmed lip heat delay, which commences to run in response to closing of the sequencer lip heat delay start switch 180, the timing circuit in the card programmer 38 produces a sequencer stepping voltage at a lip

heat delay step terminal of the programmer. This terminal is connected through a lead 191 and the lead 152 to the time delay step switch 138 of the sequencer 42. It will be recalled that this switch closes in the 10th stepping position of the sequencer. Accordingly, the stepping voltage produced by the card programmer advances the sequencer to its 11th stepping position.

It will now be understood that in the 10th stepping position of the sequencer 42, the heating power level of the crucible 22 is reduced to the programmed hold power level, the crucible is reduced, the crucible is rotated to a programmed lip heat angle to heat the crucible pouring lip and cool the molten metal within the crucible to a temperature slightly above a programmed pouring temperature, and a programmed pour temperature signal is fed to the temperature monitor. At the expiration of the programmed lip heat delay, the sequencer 42 is advanced to its 11th stepping position.

In its 11th stepping position, the program sequencer 42 recloses the controlled power lock switch 154 for the heat controller 48 and reenergizes the fixed delay timer 158 to commence running of the fixed, i.e. 1 minute, delay. Closure of switch 154 returns control of the power level setting of the heat controller 48 to the temperature monitor 52 which is currently being supplied with a programmed pour temperature signal from the card programmer. The heat controller is then adjusted to energize the crucible heating coil 23 at a controlled power level proportional to the temperature error between the temperature of the molten metal and the programmed pour temperature.

From the preceding discussion, it will be understood that in the 11th stepping position of the program sequencer 42, the crucible heating coil 23 is energized at a controlled power level, proportional to the temperature error between the molten metal temperature and the programmed pour temperature for a fixed heating delay time, i.e. 1 minute. At the expiration of this fixed delay, the sequencer 42 is advanced to its 12th stepping position.

Stepping of the program sequencer 42 to its 12th stepping position closes a normally open temperature interrogate switch 196. Closure of this switch connects a fixed delay timer 198 to the power supply lead 83 through a lead 200 and the switch contacts. The timer is thus energized by closing of the switch 196 to commence running of a fixed time delay. This time delay is selected to permit thermal stabilization of the temperature monitoring system. At the expiration of the fixed stabilization delay, the timer contacts 198a close to connect the power supply lead 83 to the temperature monitor 52 through the lead 200 and a lead 202. As will be explained later, the voltage thus applied to the temperature monitor conditions the latter to compare the temperature of the molten metal within the crucible 22 to the programmed pour temperature and to generate a sequencer backstepping voltage, forward stepping voltage, or no stepping voltage depending upon the relationships of these temperatures. Thus, if the metal temperature is less than the programmed pour temperature, the temperature monitor generates a backstepping voltage which is applied through the lead 176 to the sequencer backstepping lead 70. Under these conditions the program sequencer 42 returns to the proceeding 11th stepping position to repeat the fixed time heating step of that position at a heating power level proportional to the temperature error between the actual metal temperature and the programmed pour temperature. If the metal temperature exactly equals the programmed pour temperature, the temperature monitor 52 generates a forward stepping voltage which is applied through the lead 174 to the sequencer forward stepping lead 68 to advance the sequencer 42 to its 13th stepping position. Finally, if the metal temperature exceeds the programmed pour temperature, the temperature monitor produces no stepping voltage until the molten metal cools to the exact programmed pour temperature. When this occurs, the temperature monitor produces a forward stepping voltage for advancing the sequencer 42 to its 13th stepping position, as just explained.

At this point it is significant to note that in the 12th stepping position, no heating power level signal is supplied to the heat controller 48. Under these conditions, the heat controller energizes the crucible heating coil 23 at a reduced power level, as mentioned earlier, which permits the metal to cool to the programmed pour temperature. It is also significant to note that in the controlled heating and temperature interrogate steps numbers 8, 9, 11 and 12, no crucible angle signal is applied to the crucible drive controller 45. As will appear from the later description, under these conditions, the drive controller energizes the crucible motor 25 to rotate the crucible 22 to an upright position wherein the molten metal in the crucible is exposed to the temperature sensor 30. This permits accurate reading of the metal temperature during the temperature interrogate steps.

It is now evident that in the 12th stepping position of the sequencer 42, the temperature monitor 52 is interrogated to compare the temperature of the molten metal within the crucible 22 to the preselected pour temperature programmed into the card programmer 38. If the metal temperature is less than the programmed pour temperature, the sequencer is returned to its 11th stepping position to repeat the one minute crucible heating step at a heating power level proportional to the temperature error between the metal temperature and the pour temperature. If the metal temperature exceeds the programmed pour temperature, the system waits, applying crucible heating power at a fixed reduced power level until the metal cools to the exact pour temperature. The sequencer then advances to its 13th stepping position.

Stepping of the sequencer 42 to its 13th stepping position closes the hold power select switch 160, as described earlier, as well as two normally open switches, 204 and 208. The hold power select switch 160 remains closed in the following 14th stepping position. As noted heretofore, closure of this hold power select switch adjusts the heat controller 48 to a programmed hold power level setting. Sequencer switch 204 is a pour angle select switch, which also remains closed through the 14th stepping position. This switch completes a circuit from a pour angle terminal of the card programmer 38, through a lead 210, the switch contacts, and leads 212, 82 to the crucible drive controller 24. A programmed pour angle signal representing a final pour angle to which the crucible 22 is to be rotated during pouring, is thereby fed from the card programmer to the drive controller. As explained later, this pour angle signal merely conditions the drive controller to effect later rotation of the crucible 22 to its pour angle. In this regard, it is significant to recall that in the 13th and 14th stepping positions of the sequencer 42, the sequencer creep relay switch 74 reopens to deenergize the creep relay within the drive controller. It will appear from the later description that deenergizing of this relay in the present stepping position of the sequencer effectively locks the crucible in its current vertical position so as to prevent immediate rotation of the crucible to its pour angle in response to the incoming programmed pour angle signal. Sequencer switch 208 is a pour vacuum check switch which closes to complete a circuit from a pour vacuum terminal of the card programmer 38, through a lead 218 to the sequencer forward stepping lead 68. As will appear from the later description, the card programmer produces a stepping voltage to advance the sequencer 42 to its 14th stepping position in response to a vacuum level within the vacuum chamber 12 at least equal to a programmed pour vacuum level.

From the foregoing discussion, it will be understood that in the 13th stepping position of the sequencer 42, the heat controller 48 is adjusted to energize the crucible heating coil 23 at a programmed hold power level and the vacuum level in the vacuum chamber 12 is checked. When this vacuum level at least equals the preselected pour vacuum level programmed into the card programmer 38, the sequencer advances in its 14th stepping position.

In the 14th stepping position of the sequencer 42, the sequencer drum 62 closes a normally open pour switch 220.

Closure of this switch completes an energizing circuit from the power supply lead 83 through a lead 22, to the mold lid position controller 50. A voltage is thereby applied to the position controller which activates the lid operator 28 to raise the mold lid 26 to its upper retracted position, as explained later. Arrival of the mold lid in this retracted position closes the normally open contacts 224a, 224b of a limit switch 224 actuated by the lid operator. Closure of the switch contacts connects a pair of pour speed terminals of the card programmer 38 to the crucible drive controller 24 through leads 226a, 226b. As explained, later, a programmed pour speed signal is thereby applied to the drive controller which energizes a pour relay within the controller. This pour relay, in turn, energizes the crucible drive motor 25 to rotate the crucible 22 to its programmed pour angle at its programmed pour or tilt speed. The molten metal is thereby poured from the crucible into the now open mold 18. In this regard, it will be explained later that the programmed pour angle and pour speed and the location of the crucible pivot axis are selected to cause entrance of the molten stream into the mold cavity with virtually no splash or contact of the metal with the rim of the mold.

During rotation of the crucible 22 to its programmed pour angle, the 80° switch contacts 121 are reclosed to reenergize the fixed delay timer 122 through the sequencer 80° stepping switch 116 which is also reclosed in the current sequencer stepping position. At the expiration of the fixed time delay of the timer, its contacts 122a close to step the sequencer 42, as explained earlier. The fixed delay time of the timer 122 is selected to equal or slightly exceed the maximum pour time contemplated in the present automatic casting apparatus.

In the 14th stepping position of the sequencer 42, then, the mold lid 26 is raised to uncover the mold 18, and the crucible 22, which is currently being heated at the programmed hold power level, is rotated to its programmed pour angle at a programmed pour speed. The molten metal is thereby poured from the crucible into the mold. After completion of the pouring operation, the sequencer 42 is advanced to its final stepping position 15.

Stepping of the program sequencer 42 to its 15th stepping position opens the sequencer heat start switch 130 and hold power select switch 160 to cut all heating power to the crucible heating coil 23. The pour switch 220 also opens to deenergize the pour relay within the crucible drive controller 24. Concurrently, the creep relay switch 74 of the program sequencer closes to reenergize the creep relay within the drive controller and thereby energize the crucible drive motor 25 for rotating the crucible 22 at its creep rate to its programmed load angle. A sequencer switch 228 is closed. This switch is a vent delay start switch which completes a circuit from the power supply lead 83 through the switch contacts and a lead 230 to a vent delay power terminal of the card programmer 38. As will be explained later, the voltage thus applied to the card programmer initiates operation of the timing circuit in the programmer to commence running of a programmed vent time delay. This delay is selected to permit cooling, to a predetermined low temperature, of the metal within the mold 18 while the chamber 12 is still under vacuum. At the expiration of the vent time delay, the card programmer timing circuit produces a stepping voltage at a vent delay step terminal of the programmer. This terminal is connected through a lead 232, lead 152, and the time delay step switch 138 to the sequencer stepping lead 68. Switch 138 is currently closed, whereby the stepping voltage steps the sequencer 42. This stepping of the sequencer returns the latter to its initial home position H to complete one cycle of the casting apparatus. In the course of the final step, the vacuum-heat controller on switch 110 opens to cut power to the vacuum and heat controllers 46 and 48. From the later description, it will be seen that this action vents the vacuum chamber 12 to atmosphere. The vacuum chamber door 32 may then be opened to remove the mold 18. At this point, therefore, the casting apparatus 10 is conditioned for repetition of its casting cycle.

As noted earlier, the card programmer 38 includes an information storage medium for storing control information providing a casting program representing selected casting cycle parameters, such as those referred to in the exemplary casting cycle just described. In this instance, the information storage medium is a program card 240. FIG. 4 illustrates a typical program card for the exemplary casting cycle. The card has a number of information storage columns 242 corresponding to the different selected casting cycle parameters involved in the casting program. The parameters corresponding to the respective columns are indicated by the legends at the top of the columns. Each column is divided into a number of information storage spaces 244 corresponding to different preselected values of the respective casting cycle parameter. For example, the pour angle column contains spaces corresponding to different preselected pour angles for the crucible 22. The superheat temperature column contains spaces corresponding to different preselected superheat temperatures for the molten metal in the crucible. The melt time column contains spaces corresponding to different preselected melt times, and so on. Each space contains indicia describing its respective parameter value. A selected casting program is stored or described on the program card 240 by punching holes in selected information storage spaces of the information storage columns, as described below.

In addition to the program card 240, the card programmer 38 includes a card reader 246 which receives the program card and generates a control signal related to each casting cycle parameter of the casting program stored on the card. This card reader is illustrated in FIGS. 5 and 6. The reader includes the lid 100, referred to earlier, which is hinged to a base 248 for receiving the program card in the reading position shown. On the upper side of the base are contacts 250 arranged in columns 252 which are spaced to register with the information storage columns 242, respectively on the program card 240. The contacts in each column are disposed to register with the information storage spaces 244 in the respective information storage column of the program card. On the under side of the reader cover 100 are contacts 254, such as spring loaded contact pins or brushes, equal in number to and arranged in columns 256 in the same manner as the base contacts 250. The base and cover contacts of the card reader are thus in a manner such that when the reader cover is closed with no program card in position in the reader, the cover contacts engage their corresponding base contacts. When a program card is placed in position in the card reader, only those cover contacts which register with holes in the program card engage their corresponding base contacts through these card holes.

At this point, attention is directed to the fact that the corresponding information storage columns 242 on the program card 240 and the columns 252 of base contacts 250 and columns 256 of cover contacts 254 in the card reader 246 are individually designated by corresponding letters. In the particular program card illustrated, the first information storage column A contains pour speed information. The next two columns B and C contain chamber vacuum level information. The following eight information storage columns D-K contain crucible angle, heating power level, and metal temperature information. Finally, the last three columns M, N and P contain timing information.

The base contacts 250 in the first column 252A, which corresponds to the information storage column 242A on the program card 240 containing pour speed information are energized from the power supply 36 through a lead 257 of an electrical cable 258 and the control panel 44, as explained later. In this instance, the first column contains two base contacts which provide high and low pour speed information, respectively.

The next two columns 252B and 252C of base contacts 250, which register with the chamber vacuum level columns 242B and 242C of the program card 240 are connected through separate leads 128a of the cable 128 to the vacuum level de-

tector 16 on the vacuum chamber 12. This vacuum level detector has a number of pressure transducers 259 containing normally open contacts 260. Contacts 260 are set to close at different preselected vacuum levels in the vacuum chamber.

5 In the particular inventive embodiment shown, the number of pressure transducers 259 equals the number of base contacts 250 in each of the contact rows 252B, 252C. The corresponding contacts in the two rows are connected in series with one terminal of the corresponding transducer contacts 260. The 10 other terminals of the transducer contacts are energized from the power supply 36 through the lead 257 of the cable 258 and the control panel. Thus, closure of any transducer contacts in response to the chamber pressure dropping to the vacuum level for which the transducer is set applies a voltage to the corresponding base contacts. As will appear presently, the voltages thus applied to the base contacts in the column 252B provide heat-start vacuum level information. The voltages applied to the base contacts in column 252C provide pour vacuum level information.

20 Contained within the card reader base 248 are voltage dividers 262 for energizing the base contacts 250 in the contact columns 252D through 252K corresponding to the information storage columns 242D through 242K on the program card 240 containing crucible angle, heating power level, and

25 temperature information. These voltage dividers are energized from the power supply 36 through leads 263 of the cable 258 and the control panel. The base contacts in each column 252D through 252K are connected to taps of the corresponding voltage divider, such that the several base contacts in each column are energized at different voltage levels. These voltages provide crucible angle, heating, power level, and temperature information.

30 The card programmer 38 also embodies a timing circuit 264

35 (FIG. 7). This timing circuit has a number of input terminals 266 equal to the number of base contacts 250 in each of the contact columns 252M, 252N, 252P which register with the information storage columns 242M, 242N, 242P on the program card 240 containing time delay information. The corresponding base contacts, in the three columns, are connected in electrical series with the corresponding input terminal 266 of the timing circuit. Included in the timing circuit are a number of relay switching stages 268 and corresponding timing stages 270 equal to the number of input terminals 266. In 40 this instance, the timing circuit has six relay stages which are individually designated as 268-1 through 268-6 and six timing stages which are individually designated as 270-1 through 270-6. Each relay stage includes a relay 272 having a coil 272A, normally closed contacts 272B, and normally open contacts 272C. Each timing stage includes an automatic resetting timer 274 including a timing motor 274A and normally open contacts 274B operated by the motor.

45 The input terminals 266 of the timing circuit 264 are connected to one end of the relay coils 272A respectively. The

50 input terminals of the first five relay stages 268-1 through 268-5 are also connected in parallel, through diodes 276, to a lead 278 tied to the input end of the relay coil 272A of the final relay stage 268-6. The opposite end of the first stage relay coil is connected to the corresponding end of the second stage relay coil through two parallel circuits, one containing the normally closed contacts 272B of the first stage relay 272 and the other the normally open contacts 274B of the first stage timer 274. The corresponding end of the relay coil of each succeeding relay stage 268-2 through 268-5 is similarly connected, through its normally closed contacts 272B and the normally open contacts 274B of the corresponding timing stage, to the adjacent end of the relay coil of the following relay stage. The normally open contacts 274B of the final timing stage 270-6 are connected in series between the input end 55 of the final stage relay coil 272A and an output terminal 276 of the timing circuit 264.

60 The several timing motors 274A are connected in parallel between a pair of electrical leads 279. Connected in series with each timing motor are the normally open relay contacts 272C of the corresponding relay stage 268.

During the operation of the casting apparatus the time delay start signals referred to earlier are applied to one or more input terminals 266 of the timing circuit 264, depending upon the time delays programmed into the program card 240 currently contained within the card reader 246. Assume that such a delay start signal is applied to the third stage input terminal 266-3 of the time delay generator. Since at this time the coils 272A of all of the relays 272 are grounded through their normally closed contacts 272B, the delay signal energizes the third stage relay 272. Energizing of this relay opens its normally closed contacts 272B, thereby interrupting the ground circuit to the following relays 272. Energizing of the third stage relay also closes its normally open contacts 272C to energize the timing motor 274A of the third timing stage 270-3. The motor then runs for a predetermined time interval, at the end of which the motor closes its respective timing contacts 274B. Closure of these contacts completes an energizing circuit from the third stage input terminal 266-3, through the corresponding diode 276, lead 278, and the final stage relay coil 272A to ground. The final stage relay is thereby energized to close its normally open contacts 272C. Closure of these relay contacts energizes the final stage timing motor 274A. This motor then runs for a predetermined time interval, at the end of which the motor closes its timing contacts 274B. Closure of the latter contacts completes a circuit from the third stage input terminal 266-3 to the output terminal 276. It is evident that the above action occurs regardless of which input terminal of the timing circuit is energized.

From the above description, it will be understood that application of a time delay start signal to the input terminal 266 of any one of the first five stages of the timing circuit initiates timing operation of the circuit to generate a total time delay equal to the sum of the time delay introduced by the corresponding timing state 270 and the final timing state of the circuit. Application of a time delay start signal to the final stage generates a time delay equal to the time delay introduced by the final timing stage only.

Assume now that a time delay start signal is applied to more than one input terminal of the timing circuit 264. For example, consider the situation in which a time delay start signal is applied concurrently to the input terminals 266-3 and 266-5 of the third and fifth stages of the circuit. In this case, the timing action of the circuit proceeds in the same manner as described above except that one additional time delay is introduced into timing action. Thus, closure of the third stage timing contacts 274B by their timing motor 274A completes a ground circuit to the fifth stage relay 272. The delay signal currently applied to the fifth stage input terminal 266-5 then energizes the fifth stage relay. Energizing of the latter relay opens its normally closed contacts 272B to interrupt the ground circuit to the final stage relay 272 and closes its normally open contacts 272C to energize the fifth stage timing motor 274A. This motor then runs for a preset time, after which the motor closes its timing contacts 274B to energize the final stage relay, as before. Under these conditions, the timing circuit 264 generates a total time delay equal to the sum of the individual time delays introduced by the third, fifth, and final timing stages.

It will now be understood, therefore, that the timing circuit 264 generates a time delay in response to application of a delay start signal to any one or more of its input terminals 266. This time delay equals the sum of the individual time delays introduced by the corresponding timing stages and the final timing state 270-6. In a typical embodiment of the invention, the timers 274 of the timing states 270 are preset to generate time intervals of 1 minute, 2 minutes, 4 minutes, 8 minutes, 16 minutes, and 5 seconds respectively. The 5-second timing interval of the final timing state is provided to permit proper sequential operation of the preceding timing stages without producing an output voltage at the output terminal 276. The timers 274 are of the well-known type which automatically reset to zero and reopen their timing contacts 274B when the delay start voltage signals are removed from the input terminals 266.

It will be recalled that the card reader 246 has cover contacts 254 which are arranged to engage the base contacts 250 when the reader cover 100 is closed. The cover contacts in each of the columns 256A through 256P are connected in electrical series with a common cover contact 280. The reader base 248 is provided with common base contacts 282 which are disposed for engagement by the corresponding common cover contacts 280 through holes in the program card 240. The common base contacts 282 are individually designated as 282A through 282P according to the letter designation of their respective base contacts. For convenience in the ensuing description, these common base contacts are hereinafter referred to as terminals of the card reader. Moreover, these reader terminals are referred to in terms which relate them to their corresponding information storage columns on the program card 240. For example, the reader terminals 282A-F, 282A-S are referred to as pour speed terminals, terminal 282-B is referred to as a heat start vacuum terminal, terminal 282-C is referred to as a pour vacuum terminal, and so on. The card reader has one additional terminal 282Q, hereinafter referred to as a time delay stepping terminal, which connects to the output terminal 276 of the timing circuit 264.

It will be understood at this point, assuming the card reader 246 contains a properly prepared program card 240, that an electrical circuit path will exist between each reader terminal 282 and one of its associated base contacts 250, depending upon the particular casting cycle programmed into the programmed card 240 by selective placement of a hole H in the corresponding information storage column 242 of the program card. Thus, one of the two reader terminals 282-F, 282A-S will be energized with a voltage, hereinafter referred to as a pour speed signal, depending upon the programmed pour speed. Each of the reader terminals 282B, 282C will be energized with a voltage, hereinafter referred to as a vacuum stepping signal, whenever the vacuum level in the vacuum chamber 12 equals or exceeds the corresponding programmed vacuum level. Each of the reader terminals 282D through 282K will be energized with a voltage whose magnitude is related to the programmed value of the corresponding casting cycle parameter, such as melt angle, pour temperature, hold power level, and so on. These latter voltages are hereinafter referred to as a melt angle signal, a pour temperature signal, a hold power level signal, and so on, depending upon the particular casting cycle parameter which they represent. Each of the reader terminals 282M, 282N, 282P will be connected to one or more of the input terminals 266 of the timing circuit 264, depending upon the corresponding programmed time delay. Finally the time delay stepping terminal 282Q will be energized with a voltage, hereinafter referred to as a time delay stepping signal, whenever a voltage exists at the output terminal 276 of the timing circuit.

Turning now again to FIG. 3, it will be seen that the melt angle terminal 282D of the card reader 246 is connected to the crucible drive controller 45 through the lead 118, melt angle select switch 114 of the program sequencer 42, and leads 120, 82. Closure of the melt angle select switch thus feeds a melt angle signal from the card reader to the drive controller. The vacuum stepping terminal 282B of the card reader is connected to the forward stepping lead 68 of the program sequencer through the lead 126 and the sequencer vacuum stepping switch 124. Accordingly, closure of this switch with a vacuum level in the vacuum chamber 12 equal to or greater than the programmed heat start vacuum level feeds a vacuum stepping signal to the program sequencer 42 which steps the latter in the forward direction. The melt power terminal 282G of the card reader 246 is connected through the lead 142, the sequencer melt power select switch 132, and the lead 144 to the heat controller 48. Closure of the sequencer melt power select switch 132, therefore, feeds a melt power signal from the card reader to the heat controller. The superheat temperature select terminal 282J of the card reader is connected to the temperature monitor 52 through the lead 146, the sequencer superheat temperature select switch 134 and lead

148. Closure of the superheat temperature select switch thus feeds a superheat temperature signal from the card reader to the temperature monitor. The melt time delay start terminal 282M of the card reader is connected through lead 150 and the melt delay power switch 136 of the sequencer 42, to the power supply lead 83. When this switch is closed, therefore, a voltage is applied to the reader melt time delay start terminal. The hold power terminal 282H of the card reader is connected to the heat controller 48 through the lead 164, the hold power select switch 160 of the program sequencer 42, and the lead 166. Accordingly, closure of this switch feeds a hold power level signal from the card reader to the heat controller. The reader hold power terminal 282H and the full controlled power level terminal 282I are directly connected to the temperature monitor 52 through leads 285a, 285b, respectively. The lip heat angle terminal 282E of the card reader is connected to the crucible drive controller 24 through the lead 184, the sequencer lip heat angle select switch 178, and the leads 186, 82. When the lip heat angle select switch is closed, therefore, a lip heat angle signal is fed from the card reader to the drive controller. The reader lip heat delay start terminal 282N is connected through the lead 188 and the sequencer lip heat delay power switch 180 to the power supply lead 83. Closure of this switch thus applies a voltage to the lip heat delay start terminal of the card reader. The pour temperature terminal, 282K of the card reader connects, through the lead 189, the pour temperature select switch 182 of the sequencer 42, and the leads 190, 148 to the temperature monitor 52. Closure of the pour temperature select switch, therefore, feeds a pour temperature signal to the temperature monitor. The pour angle terminal 282F of the card reader is connected to the crucible drive controller 24 through the lead 210, the sequencer pour angle select switch 204, and the leads 212, 82. Accordingly, closure of the pour angle select switch feeds a pour angle signal from the card reader to the drive controller. The pour vacuum terminal 282C of the card reader connects to the forward stepping lead 68 of the program sequencer 42 through the lead 218 and the sequencer pour vacuum stepping switch 208. Closing of this switch with the interior of the vacuum chamber 12 at a vacuum level equal to or greater than the programmed pour vacuum, therefore, feeds a stepping voltage to the program sequencer to step the latter. The two pour speed terminals 282A_E, 282A_S of the card reader are connected through the mold lid limit switch 224, normally open contacts 220a of the sequencer pour switch 220, and leads 226a, 226b to the crucible drive controller 45 to feed a pour speed signal to the drive controller for controlling the tilt rate of the crucible 22 during the actual pouring operation. The vent delay start terminal 282P of the card reader is connected to the power supply lead 83 through the lead 230 and the vent delay power switch 228 of the program sequencer. Closure of this sequencer switch, therefore, applies a voltage to the vent delay start terminal of the reader. Finally, the time delay stepping terminal 282Q of the card reader is connected through the lead 152 and the time delay stepping switch 138 to the forward stepping lead 68 of the program sequencer. Accordingly, when the sequencer switch 138 is closed, an output voltage produced by the reader timing circuit 264 is applied to the sequencer to step the latter.

The card reader also includes a load angle terminal 282L which is energized directly, i.e. not through the program card 240, from an adjustable voltage divider 262L, terminal connects through lead 80 to the sequencer switch 72 to provide a preset load angle signal to the drive controller.

The crucible drive controller 45 is detailed in FIG. 8. This controller comprises a servosystem 286 for energizing the crucible drive motor 25 in response to the various crucible angle and tilt rate signals fed to the controller. Included in servosystem is a servoamplifier 288, an input circuit 290 for the amplifier, a crucible position feedback signal circuit 292, and a crucible tilt rate feedback circuit 294. The output of the servoamplifier is connected to the crucible drive motor 25 through leads 287. The amplifier input circuit 290 includes an

error detector 296, in this instance a pair of summing resistors 298, 300, connected to the servoamplifier 288 through a speed select relay bank 304. Position feedback circuit 292 includes a feedback signal generator 306 for generating a feedback signal related to the crucible angle. This feedback signal is applied to one terminal of the error detector 296. The other terminal of the error detector is connected to the crucible angle select lead 82 of the control system 34. The feedback signal generator 306 shown is a potentiometer having a wiper 306a coupled to the crucible and a resistor 306b which is energized from the power supply 36 through a lead 307 in the cable 258 and the control panel. The crucible angle voltage dividers in the card reader 246 and the feedback resistor 306b are energized with regulated DC voltages of opposite polarity. Accordingly, the crucible angle signals from the card reader and the crucible position feedback signal from the feedback signal generator 306 are DC voltage signals of opposite polarity. These signals are combined in the error detector 296 to produce an error signal which is fed through the speed select relay bank 304 to the servo amplifier 288. The magnitude of this error signal is related to the angular error between the current position of the crucible 22 and the crucible angle represented by the crucible angle signal fed to the drive controller. The polarity of the error signal represents the direction of the angular error, that is the direction in which the crucible must be rotated to bring the crucible to the angular position represented by the crucible angle signal.

The speed select relay bank 304 includes three relays 308, 310, and 312. Relay 308 is the creep relay referred to earlier and is connected to the lead 86 of the sequencer creep relay switch 74 so as to be energized when this switch is closed. The creep relay has normally open contact 308a connected in series with a variable resistor 314 between the output of the error detector 296 and the servoamplifier 288. Relay 310 is a fast pour relay and is connected through the lead 226a and the mold lid limit switch 224 to the fast pour terminal 282A-F of the card reader 246 so as to be energized by a fast pour signal from the reader. This relay has normally open contacts 310a connected in series with a variable resistor 316 between the error detector 296 and the servoamplifier 288. Finally, relay 312 is a slow pour relay which is connected to the slow pour terminal 282A-S of the card reader through the lead 266b and the limit switch 224 so as to be energized by a slow pour signal from the reader. Relay 312 has normally open contacts 312a connected in series with the variable resistor 316 and a variable resistor 318 between the error detector 296 and the servoamplifier 288.

As noted above, the servosystem 286 has a crucible tilt rate feedback circuit 294. This feedback circuit includes a means 320, in this instance a tachometer generator coupled to the crucible 22 for generating a feedback signal related to the rotation rate of the crucible. This rate feedback signal is applied to the servoamplifier 288. The servoamplifier 288 is energized from the power supply 36 through a lead 319 of the cable 258 and the control panel.

From the foregoing description, it will be understood that the crucible drive controller 24 is activated in response to each crucible angle signal from the card reader 246 and concurrent energizing of one of the speed select relays 308, 310, 312 to drive the crucible 22 to the angle represented by the angle signal at a rotation or tilt rate determined by the variable resistance or resistances 314, 316, 318 in circuit with the energized speed select relay. According to the present invention, the creep resistance 314 is adjusted to cause rotation of the crucible 22 at a selected creep rate which is relatively slow to prevent jarring of the crucible and splashing of its molten contents. The fast pour resistance 316 and slow pour resistance 318 are adjusted to cause rotation of the crucible at selected fast and slow tilt rates which will effect accurate entrance of the molten stream into the mold 18 without contact of this stream with the mold rim throughout the pouring angle. In this regard, it should be noted that the pour speeds are determined experimentally and vary inversely with the level of the molten

metal in the crucible. That is to say, the fast pour speed will be used when the level of the molten metal in the crucible is within the range between a minimum level and some intermediate level. The slow pour speed will be used in the range between the intermediate level and the maximum level of molten metal in the crucible. Obviously, additional pour speeds may be programmed into the apparatus to permit more accurate control of the molten stream during the pouring operation and thereby assure accurate entrance of the molten stream into the mold 18 without contact of the metal with the mold rim. Energizing of the creep relay 308 with no crucible angle signal applied to the crucible drive controller 24 activates the latter to drive the crucible 22 to one limit of its rotation. In this instance, the limiting position to which the crucible 22 is driven is an upright position wherein the molten metal within the crucible is exposed to the thermal sensor 30 for the accurate response of the sensor to the temperature of the molten metal. Suitable limit switches (not shown) are provided for arresting the crucible in its limiting positions.

Turning next to FIG. 9, the vacuum system of the casting apparatus is detailed. This vacuum system includes the vacuum pumping means 14 and the vacuum controller 46 for the pumping means. In an actual pouring apparatus according to the invention, the vacuum pumping means may comprise a multistage vacuum pumping system embodying a number of valves which are operated in sequence to pump down the vacuum chamber 12 in stages to the desired vacuum level. Vacuum controller 46, in this case, will include the necessary circuitry for automatically operating the valves in the proper sequence in response to activation of the vacuum controller in the manner hereinafter described. However, for convenience, the vacuum pumping means 14 has been simply illustrated as comprising a vacuum pump 324 driven by a motor 326. The pump intake communicates to the interior of the vacuum chamber 12 through a solenoid valve 328. When deenergized, this valve vents the chamber to atmosphere. When energized, the valve communicates the chamber to the pump. The motor 326 is energized from the power supply 36 through leads 329 of the cable 258 and the control panel. Valve 328 is connected to the power supply 36 through the control panel and a lead 330 containing normally open contacts 332a of a vacuum start relay 332 within the vacuum controller 46. The relay coil 332b is connected to the power supply lead 83 through the lead 113 and the vacuum-heat controller on switch 110 of the program sequencer 42. As will appear presently, the pump motor 326 is energized upon actuation of the switches 58 on the control panel 44 at the outset of the casting cycle. However, actual pumpdown of the vacuum chamber 12 does not commence until the valve 328 is energized by energizing of relay 332 in response to closure of the sequencer switch 110. Closure of this switch communicates the chamber to the pump to commence pumping-down of the chamber to or below the vacuum level represented by the vacuum level information programmed into the card reader 246, as hereinafter explained.

FIG. 10 details the temperature monitor 52. This monitor includes a servosystem 334 for generating an output voltage proportional to the temperature of the molten metal in the crucible 22. The servosystem has a servoamplifier 336 whose output feeds a servomotor 338. Servomotor 338 drives a feedback signal generator 340, in this instance a potentiometer having a wiper 340a and a resistor 340b. Resistor 340b is energized with a DC voltage from the power supply 36 through a lead 341 of the cable 258 and the control panel. The amplifier input is connected to the signal generator 340 and the temperature sensor 30 through an error detector 342, shown as a pair of summing resistors 344. The particular temperature sensor 30 illustrated is an infrared detector which is disposed to view the molten metal in the crucible 22 through a window 343 in the vacuum chamber 12 when the crucible occupies its upright position and to generate a DC voltage proportional to the metal temperature, and of opposite polarity to the feedback voltage to the amplifier 336. Accordingly, the shaft of the servo motor 338 continuously assumes a position related

to the metal temperature. The servomotor 338 also drives an output signal generator 346, in this instance a second potentiometer having a wiper 346a and a resistor 346b. Resistor 346b is energized from the power supply 36 through a lead 347 of the cable 258 and the control panel. Signal generator 346 produces a DC output voltage signal proportional to the output voltage of the temperature sensor 30 and thus hence proportional to the molten temperature.

Also included in the temperature monitor 52 is a second 10 servo system 348 for generating an output related to the temperature error between the temperature of the molten metal in the crucible 22 and the temperatures represented by the programmed temperature signals fed to the temperature monitor from the card reader 246. Servosystem 348 has a servoamplifier 350 which is energized from the power supply 39 through a lead 351 of the cable 258 and the control panel. The amplifier output feeds a servomotor 352 through the normally closed contacts 354a of a controlled power lock relay 354. The coil 354b of this relay is connected to the power supply lead 63 through the lead 156 of the controlled power lock switch 154 of the program sequencer 42. Closure of the switch 154 thus energizes the lock relay 354 to open its contacts 354a and thereby disconnect the servomotor 352 from the amplifier 350. Servomotor 352 drives a feedback signal generator 356, in this instance a potentiometer having a wiper 356a and a resistor 356b. Resistor 356b is energized with a DC voltage from power supply 36 through leads 357a, 357b of the cable 258 and the control panel.

30 The input of the servoamplifier 350 is connected to the temperature select lead 148 from the temperature select switches 134, 182 of the program sequencer 42 and to the metal temperature signal generator 346 of the temperature monitor 52 through a pair of error detectors 358 and 360. The first error detector 358, which in this instance comprises a pair of summing resistors 362, combines the temperature select signal fed to the temperature monitor through the temperature select lead 148 and the metal temperature signal from the temperature signal generator 346 to produce an error signal 35 40 proportional to the temperature error between programmed temperature represented by the temperature select signal and the temperature of the molten metal in crucible 22. In this regard, it should be noted that the pour and superheat temperature voltage dividers 262 in the card reader are energized with a DC voltage of opposite polarity to the output voltage of the signal generator 346 from the power supply 36 through a lead 361 of the cable 258 and the control panel. The second error detector 360, comprising in this instance a pair of summing resistors 364, combines this temperature error signal with the 45 feedback signal from the feedback signal generator 356 to produce a position error signal which is fed to the servoamplifier 350. It will now be understood that a temperature select signal applied to the temperature monitor 52 through the temperature select lead 148 with the power lock relay 354 deenergized activates the servomotor 352 to drive its shaft to a position related to the temperature error between the programmed temperature corresponding to the temperature select signal and the actual temperature of the molten metal in the crucible 22.

50 The servomotor 352 drives an output signal generator 366, represented in this instance by a potentiometer having a resistor 366a and a wiper 366b. The wiper is connected to the motor shaft so as to be positioned along the resistor in accordance with the temperature error between the actual metal temperature and the programmed temperature represented by the temperature select signal fed to the temperature monitor 52. One end C of the resistor 366a is connected to the lead 285b from the full controlled power level terminal 282l of the card reader 246. An intermediate tap H of the resistor is connected to the bold power level 282H of the card reader through the lead 285a. The lead 159b connects the wiper 366b to the heat controller 48. Arranged in series in the lead 159b are the normally open contacts 368a of a monitor output relay 55 60 65 70 75 368. The relay coil 368b is connected to the lead 156. The

relay is thus energized to close its contacts 368a and feed the monitor output signal to the heat controller 48 when the power lock relay 354 is energized to disconnect the output signal generator motor 352 from its servoamplifier 350.

The temperature monitor 52 is so organized that when the error detector 358 produces a null signal, which occurs when the temperature of the molten metal in the crucible 22 exactly equals the temperature corresponding to the temperature select signal fed to the monitor, the wiper arm 366b of the output signal generator 366 assumes a stationary position in which the arm contacts the hold power level tap H of the resistor. This position of the arm is hereinafter referred to as its hold power position or midposition. In this position, a voltage signal, which represents the hold power level programmed into the card reader 246, is fed through the lead 159b to the heat controller. This hold power level is based on the weight of the metal charge to be poured and is determined empirically or experimentally to be heating power level required to maintain the molten charge at the programmed pour temperature. A temperature select signal input to the temperature monitor which represents a programmed temperature higher than the current temperature of the molten metal activates the servosystem 348 to drive the wiper arm 366b toward the controlled power level terminal C of the resistor 366a to a final position related to the temperature error. As the wiper arm approaches and finally contacts this terminal, the voltage signal delivered to the heat controller 48 through lead 159b progressively increases to and finally equals the voltage applied to the terminal. This voltage represents the full controlled power level programmed into the card reader and is based on the weight of the metal charge. In the ensuing description, the terminal position of the wiper arm in which it contacts the terminal C is referred to as its full control power level position. Conversely, a temperature select signal which represents a programmed temperature less than the molten metal temperature, activates the servosystem 348 to drive the wiper arm in the opposite direction to progressively decrease the voltage signal delivered to the heat controller.

From this description, it is evident that the wiper arm 366b of the temperature monitor output signal generator 366 assumes a position at the side of the hold power level tap H nearest the full controlled power level terminal C, i.e. at the upper side of the tap in FIG. 10, when the molten metal temperature is colder than the programmed temperature corresponding to the temperature select signal fed to the monitor 52 and a position at the opposite or lower side of the tap when the molten metal temperature is hotter than the programmed temperature corresponding to the incoming temperature select signal. For convenience in the ensuing description, the region above the hold power tap H in FIG. 10 is referred to as the low temperature side of the tap and the lower region is referred to as the high temperature side of the tap.

Also included in the output signal generator 366 of the temperature monitor 52 are three wiper arm position sensing limit switches 370, 372, and 374. Limit switch 370 has a movable contact 370a and two fixed contacts 370b, 370c. Switch 372 has a movable contact 372a and fixed contacts 372b and 372c. Switch 374 has a movable contact 374a and a single fixed contact 374b. The movable contact 370a of switch 370 is operated by the wiper arm 366a of the generator in such a way that the switch is closed to its fixed contact 370b when the wiper arm is at the low temperature (i.e. upper) side of the generator hold power tap H. When the wiper arm is at the high temperature (i.e. lower) side of this tap H, the switch is closed to its contact 370c. During movement of the wiper arm 366b from one side of the hold power tap H to the other, the switch 370 remains in its current position until the wiper arm passes through its midposition of contact with the tap, such that the switch is closed to one fixed contact or the other in the midposition of the wiper arm. Switch 372 is operated by the wiper arm 366b in such a way that the switch is closed to its fixed contact 372b when the arm is at the low temperature side of the hold power tap H and to its fixed contact 372c when the

arm is in its midposition or at the high temperature side of the tap. Finally, switch 374 is operated by the wiper arm 366c in such a way that the switch is closed to its single fixed contact 374b when the arm is located in its midposition or at the cold temperature side of the hold power tap H. The switch is opened when the wiper arm is located at the high temperature side of the tap.

The movable contact 370a of limit switch 370 is connected to the power supply lead 83 through lead 172, fixed time delay 10 relay contacts 170a, lead 168, and the temperature interrogate switch 162 of the program sequencer 42. The fixed switch contacts 370b, 370c are connected to the back and forward stepping leads 70, 68, respectively, of the program sequencer 42 through the leads 176 and 174, respectively. 15 The movable contact 372a of the limit switch 372 is connected to the power supply lead 83 through the lead 202, fixed time delay relay contacts 198a, lead 200, and the sequencer temperature interrogate switch 196. The fixed contacts 372b, 374b of limit switches 372, 374 are connected to the sequencer back and forward stepping leads 70, 68, respectively, through the circuit paths traced out above, including the leads 176, 174. Finally, the fixed contact 372c of limit switch 372 is connected to movable contact 374a of limit switch 374.

From the foregoing description, it is evident that closure of the sequencer temperature interrogate switch 162 applies a stepping voltage to the backstepping lead 70 of the program sequencer 42 through the fixed contact 370b of limit switch 370 if the programmed temperature represented by the temperature select signal input to the temperature monitor 52 exceeds the actual temperature of the molten metal in the crucible 22. If the programmed temperature represented by the temperature select signal is lower than the metal temperature, closure of the sequencer switch 162 applies a stepping voltage 30 to the sequencer forward stepping lead 68 through the fixed contact 370c of limit switch 370. Similarly, closure of sequencer temperature interrogate switch 196 applies a stepping voltage to the sequencer backstepping lead 70 through the fixed contact 372b of limit switch 372 if the programmed temperature represented by the temperature select signal to the temperature monitor exceeds the metal temperature. On the other hand, if the metal temperature exceeds the programmed temperature represented by the temperature select signal, closure of the sequencer switch 196 does not 45 deliver a stepping voltage to the sequencer 42 until the limit switch 374 closes in response to cooling of the metal to the programmed temperature. A stepping voltage is then applied to the sequencer forward stepping lead 68 through the fixed contact 372c of limit switch 372 and the fixed contact 374b of limit switch 374.

Turning next to FIG. 11, the heat controller 48 is detailed. This controller comprises a DC controlled induction heater power supply 376 for energizing the induction heating coil 23 of the crucible 22 at a heating power level determined by the DC control signal applied to the power supply. This power supply may comprise any suitable DC controlled induction heater power supply, such as a motor driven generator or alternator having a DC controlled field. The power supply is energized through a lead 377 of the cable 258 and the normally open contacts 378a of a heat controller power relay 378. The coil 378b of the relay is connected through the lead 113 and the vacuum-heat controller on switch 110 of the program sequencer 42 to the power supply of 83. Accordingly, 55 closure of the sequencer switch 110 energizes the relay 378 to close its contacts 378a and thereby energize the induction heater power supply 376. The DC controlled heating power level regulating circuit of the power supply 376 is connected to the melt and hold power level terminals of the card reader 246 through the lead 144 and the heating power level select switches 132, 160 of the program sequencer 42 and to the power level control signal generator 366 of the temperature monitor 52 through the lead 159b.

The output of the induction heat power supply 376 is connected to the crucible heating coil 23 through leads 380 and

the normally open contacts 92b of the MLC relay 92, referred to earlier. In this regard, it will be recalled that the MLC relay has normally open contacts 92a connected in series with the sequencer switch 90 between power supply lead 83 and the sequencer forward stepping lead 68. The coil 92c of MLC relay 92 is connected to the main power supply 36 through a lead 382 of the cable 258 and the control panel. The heat controller power relay 378 has a pair of normally closed contacts 378c connected in series in the lead 382. MLC relay coil 92c is also connected to the power supply lead 83 through the lead 140 and the heat start switch 130 of the program sequencer 42.

As will be explained presently, the MLC relay 92 is energized at the outset of the casting cycle through the then closed heat controller relay contacts 378c by actuation of the control panel switches 56, 58. Subsequent energizing of the power relay 378 by closure of the sequencer vacuum-heat control on switch 110 deenergizes the MLC relay to disconnect the induction heater power supply 376 from the crucible heating coil 23. Later in the cycle, the MLC relay is again energized to connect the induction heating power supply to the crucible heating coil by closure of the heat start switch 130 of the sequencer 42.

FIG. 12 details the mold lid operator 28 and its controller 50. In this instance, the operator 28 comprises a hydraulic cylinder 384 mounted on the ceiling of the vacuum chamber 12 directly over the mold 18, and containing a plunger 386 which carries the mold lid 26. The mold lid operator 50 comprises a source 388 of hydraulic fluid under pressure and a solenoid valve 400 for controlling hydraulic fluid flow between the fluid source and the ends of the cylinder 384. Energizing of the valve solenoid 402 shifts the valve spool 404 to its left-hand limiting position of FIG. 12. In this position, a motor driven pump 406 of the hydraulic fluid source 388 pumps hydraulic fluid under pressure from a reservoir 408 through the valve and a fluid conduit 410 to the lower end of the cylinder 384 to raise the mold lid 26. Hydraulic fluid in the upper end of the cylinder then returns to the reservoir through a fluid conduit 412, the solenoid valve and a return conduit 414. Energizing of the valve solenoid 416 shifts the valve spool 404 to its right-hand limiting position. In this position, fluid is pumped from the reservoir through the valve and the fluid conduit 412 to the upper end of the cylinder to lower the mold lid 26. Fluid in the lower end of the cylinder is then returned to the reservoir through the fluid conduit 410 and a return conduit 418.

Valve solenoid 416 is energized from the power supply 36 through a lead 420 of the cable 258 and the switch 59 on the control panel 44. Valve solenoid 402 is connected to the power supply lead 83 through the lead 222 and the sequencer pour switch 220 so as to be energized by closure of the latter switch.

As noted earlier, the present casting apparatus is conditioned for its semiautomatic casting cycle by performing at the outset of the cycle certain initial operations which are represented in this disclosure by actuation of the control panel switches 56 and 58. Actuation of the switch 56 initiates this cycle. Switch 58 is a power switch whose actuation energizes the control system of the casting apparatus from the power supply 36. Referring to FIG. 2, this power supply includes an unregulated DC source 36a, regulated DC sources 36b, 36c which produce regulated DC voltages of positive and negative polarity relative to ground, and high and low AC voltage sources 36d, 36e. These power sources are connected to a switching relay 422 in the control panel 44 through power input leads 424a, 424b, 424c, 424d, and 424e. Switch 56 comprises the earlier mentioned normally open contacts 56a which are connected in series with the sequencer automatic power-on switch 76. Switch 58 has normally open contacts 58a arranged in series in a lead 426 connecting the DC lead 424a to the coil 422f of the switching relay 422. Switch 56 is pressed to close its contacts 56a and reopens when released. Switch 58 remains in each of its opened and closed positions

until moved to the other position. From the foregoing description, it will be understood that closure of switch 58 energizes the holding relay 422.

Switching relay 422 has normally open contacts 422a, 422b, and 422c which close when the relay energizes. Relay contacts 422a connect DC source 36a to the card reader lead 257 (FIG. 6), the vacuum controller lead 330 (FIG. 9), and the heat controller lead 382 (FIG. 11). Relay contacts 422b connect DC source 36b to the card reader lead 263 and the temperature monitor lead 375a (FIG. 10). Relay contacts 422c connect the DC source 36c to drive controller lead 307 (FIG. 8) and the temperature monitor leads 341, 347, 351b. Relay contacts 422d connect the AC source 36d to the heat controller lead 377. Relay contacts 422e connect the AC source 36c to the timing circuit lead 279 (FIG. 7), the drive controller lead 319, the vacuum pump motor lead 329 (FIG. 9), the temperature monitor lead 351, and the lid controller pump motor lead 406a (FIG. 12). Each source provides an output voltage suitable for energizing its respective elements. Source 36a, for example, provides a relatively low DC solenoid operating voltage. Sources 36b and 36c provide relatively low regulated servo control voltages. Source 36d provides a relatively high AC voltage suitable for induction heating power generation. Source 36c provides a relatively low AC voltage for powering the timing motors and servoamplifiers.

As noted earlier, the control panel 44 also includes a switch 59 for lowering the mold lid 26 after the mold 18 is placed in the vacuum chamber 12. This switch has normally open contacts 59a through which the valve solenoid lead 420 of the mold lid operator 50 is connected to the DC source 36a. Closure of the switch contacts 59a thus energizes the lid controller valve 400 to lower the mold lid 26 to its target position. The switch 59 is of the type which automatically reopens when released. The valve is subsequently reenergized to raise the lid during the casting cycle, as noted earlier. If desired, however, an additional energizing circuit for the valve, including a switch on the control panel, may be provided to raise the lid. At this point, it should be noted that the hydraulic pump 388 is assumed to have a maximum delivery pressure, such that the pump can continue to operate without damage to the hydraulic system when the pumper 38b is stationary at the ends of its strokes.

The control panel 44 may also include manual override switches 428, 430, 432, 434, and 436 to permit manual control of the crucible position at any time in the casting cycle. In this case, switch contacts 438a (FIG. 8) are connected in the angle select lead 82 to the crucible drive controller 45. Switches 428, 430, 432, 434, and 436 have contacts 428a, 430a, 432a, 434a, and 436a, respectively. The several contacts 428a, 430a, 432a, 434a, 436a, and 438a are coupled by a conventional interlocking mechanism, represented by the dashed line 440 so that closure of any given set of the contacts automatically opens the remaining contacts. Contacts 438a are operated connected to the control panel switch button 56, through a connection represented by the dashed line 442, so that depression and release of the button to initiate the automatic casting cycle closes the contacts 438a and opens contacts 428a through 436a.

Associated with the manual override switches 428 through 436 is a voltage divider 444 which is energized from the regulated positive DC source 36b. This voltage divider has adjustable wipers 446 through 452 connected through the switch contacts 428a through 434a, respectively, to a common lead 454 of the cable 258. The grounded end of the voltage divider is connected to the lead 454 through the switch contacts 436a. Lead 454 is tied to the same input terminal of the crucible drive controller error detector 296 (FIG. 8) as the crucible angle select lead 82 from the card reader 246.

From this description, it is evident that depression of the control panel button 56 to initiate the automatic casting cycle opens the manual override contacts 428a through 436a and closes the contacts 438a in the crucible drive controller 45 to condition the latter to respond to the programmed crucible

angle signals from the card reader 246. Closing of any one of the manual override switches 428 through 436 during the casting cycle closes the corresponding override switch contacts 428a through 436a and opens the drive controller contacts 438a. A crucible angle voltage signal is then fed from the manual override voltage divider 444 to the crucible drive controller 45 to activate the latter for driving the crucible 22 to the angle represented by the override signal. The wipers 446 through 452 of the voltage divider are set to provide override signals representing pour, load, lip heat, and melt angles for the crucible, as indicated by the legends in FIG. 2. The override switch 436 provides a vertical signal to the drive controller. Normally, the manual override means will be set to provide the same crucible angles as the casting program and will be used in case of malfunction in the program controlled crucible-positioning system. The manual override means can also be used for manual control of the crucible position under other operating conditions.

The operation of the casting apparatus will now be reviewed in relation to the exemplary casting cycle discussed earlier. The apparatus is conditioned for this automatic casting cycle by actuation of the control panel switch 58 to energize the control system 34. The switch 56 is then actuated to close its contacts 56a and thereby step the program sequencer 42 from its home position H to its first stepping position. As noted, contacts 56a reopen when switch 56 is released. Also, actuation of switch 56 closes the crucible drive controller contacts 438a to condition the drive controller 45 for program control of the crucible position.

In the first stepping position, the sequencer load angle select switch 72 closes to feed a load angle signal from the card reader 246 to the crucible drive controller 45 and the creep relay switch 74 closes to energize the crucible drive motor 25 to rotate the crucible 22 at a creep rate to its load angle wherein the metal charge can be placed in the crucible. Energizing of the control system 34 by actuation of the panel switch 58 energizes the MLC relay 92 in the heat controller 48. Its contacts 92a, 92b then close to indicate the operational readiness of the heat controller 48 to supply heating power to the crucible induction heating coil 23. Closure of the relay contacts 92a steps the sequencer 42 to its second stepping position.

In the second stepping position, the crucible 22 is loaded with the metal to be poured and a heated mold 18 is placed in the vacuum chamber 12. The control panel switch 59 is then closed to lower the mold lid 26 to signify that the mold is in chamber and the mold is located in proper pouring position by aligning it with the lowered lid. Arrival of the lid 26 in its lowered position closes the lid down limit switch contacts 94 to apply a stepping voltage to the sequencer 42 through its currently closed lid down check switch 96.

During the third step of the casting cycle, a properly prepared casting program card 240 is inserted into the card reader 246 and its cover 100 is closed. These actions close the contacts 102, 103 in circuit with the now closed reader check switch 104 of the program sequencer 42 to step the latter in its fourth stepping position.

The casting apparatus is now conditioned for the automatic position of its casting cycle. This portion of the cycle is initiated by closing the vacuum chamber door 32. Closing the door closes the door contacts 108 to apply a stepping voltage to the sequencer 42 through its currently closed door closed check switch 106. The sequencer then advances to its fifth stepping position.

In the fifth stepping position of the sequencer 42, its vacuum heat controller on switch 110 closes to energize the vacuum controller relay 332 and the heat controller relay 378. Energizing of the vacuum controller relay closes its contacts 332a to energize the vacuum pump valve 328 and thereby shift this valve to its pump position for starting pumpdown of the vacuum chamber 12. Energizing of the heat controller relay 378 opens its contacts 378c to deenergize the MLC relay 92 and thereby disconnect the induction heater power

supply 376 from the crucible heating coil 23. The relay contacts 378a close to activate the power supply 376 for generating heating power for the coil. In the fifth stepping position, the sequencer melt angle select switch 114 closes to feed a programmed crucible melt angle signal to the crucible drive controller 55. This signal activates the controller to drive the crucible 22 at the creep rate to the programmed melt angle. During rotation of the crucible to its melt angle, the 80° switch 121 closes to energize the fixed delay timer 122 through the now closed sequencer 80° stepping switch 116. At the end of its fixed delay time, the timer contacts 122a close to step the sequencer 42 to its sixth stepping position. The timer then resets in readiness for its next timing cycle.

Stepping of the sequencer 42 to its sixth position closes the sequencer heat start vacuum switch 124. This action effectively connects the vacuum level detector 16 to the sequencer stepping lead 68 through the card reader 246 so that reduction of the vacuum level in the vacuum chamber 12 to the programmed heat start vacuum level applies a stepping voltage to the sequencer for advancing the latter to its seventh stepping position.

In the seventh stepping position, the sequencer heat start switch 130 closes to reenergize the MLC relay 92 in the heat controller 48 and thereby connect the induction heater power supply 376 to the crucible heating coil 23. The sequencer melt power switch 132 also closes to feed a programmed melt power signal from the card reader 246 to the heat controller. These actions effect energizing of the crucible heating coil at the programmed melt power level. In the current stepping position, the sequencer superheat temperature select switch 134 and melt time delay switch 136 also close to feed a superheat temperature signal to the temperature monitor 52 and activate the card reader timing circuit 264 to commence running of a programmed melt time. At the expiration of this melt time, the timing circuit feeds a stepping voltage to the program sequencer 42 through the currently closed sequencer time delay stepping switch 138 for stepping the sequencer to the eighth stepping position.

In the eighth stepping position, no crucible angle information is supplied to the crucible drive controller 45. Under these conditions, the drive controller energizes the crucible drive motor 25 to rotate the crucible 22 to an upright position wherein the molten metal in the crucible is exposed to the thermal sensor 30. The sequencer power lock switch 154 closes to energize the power lock relay 354 and the output relay 368 in the temperature monitor 52. Energizing of the lock relay 354 disconnects the monitor servomotor 352 from its amplifier 350 to lock the wiper arm 366b of the output signal generator 366 in a fixed position. Energizing of the output relay 368 connects the wiper arm to the power level control terminal of the induction heater power supply 376 in the heat controller 48. The power level setting of the power supply is thereby adjusted to energize the crucible heating coil 23 at the full controlled power level programmed into the card reader 246.

In this latter regard, it is significant to note that in the eighth stepping position, no programmed heating power level information is fed from the card reader 246 to the heat controller 48. It is also significant to recall that a programmed superheat temperature signal is fed from the card reader to the temperature monitor in the seventh and eighth stepping positions. This signal represents a metal temperature substantially higher than the actual molten metal temperature at this point. This is due to the fact that the melt delay time of the seventh step is selected to heat the metal to a temperature less, by a preselected amount, than the programmed superheat temperature, as noted earlier. As a consequence, the programmed superheat temperature signal fed to the temperature monitor 52 in the seventh stepping position activates the monitor output servo 348 to drive its wiper arm 366b to the upper limit of its travel in FIG. 10, wherein the arm engages the full controlled power level terminal C of the output resistor 366a and a programmed full controlled power level signal is fed to the heat controller.

Closure of the sequencer switch 154 also energizes the fixed delay timer 158 to commence the running of a fixed melt delay time, typically 1 minute. At the expiration of this delay, the timer contacts 158a close to step the sequencer 42 to its ninth stepping position, whereupon the timer resets in readiness for its next timing cycle.

In the ninth stepping position, the sequencer hold power switch 160 closes to feed a programmed hold power signal to the heat controller 48 for adjusting its power level to the programmed hold power level. The temperature interrogate switch 162 also closes to energize the fixed delay timer 170 which introduces a delay to permit thermal stabilization of the temperature monitor 52. At the end of this delay, the timer contacts 170a close to feed a temperature interrogate signal to the movable limit switch contact 370a of the temperature monitor 52. During the thermal stabilizing delay, the wiper arm 366b of the monitor servo 348 assumes a position related to the temperature error between the metal temperature and the programmed superheat temperature represented by the superheat temperature signal currently being fed to the monitor from the card reader 246. If the wiper arm 366b assumes a position above, i.e. at the cold side of, the hold power tap H of its resistor 366a in FIG. 10, indicating that metal temperature is below the programmed superheat temperature, a stepping voltage is applied to the backstepping lead 70 of the sequencer 42 through the upper monitor contact 370b. The sequencer is then returned to its eighth stepping position to repeat the fixed time heating operation of the latter step at a heating power level proportional to the temperature error. If wiper arm 366b assumes a position at or below, i.e. at the hot side, of the hold power tap H, indicating that the molten metal has achieved its programmed superheat temperature, a stepping voltage is applied to the sequencer forward stepping lead 68 through the lower monitor contact 370c in FIG. 10. The sequencer then advances to its 10th stepping position.

Advancement of the sequencer 42 to its 10th stepping position closes its lip heat angle select switch 178 to feed a programmed lip heat angle signal to the crucible drive controller 45. The controller then rotates the crucible 22 to the lip heat angle at the creep rate. The sequencer lip heat delay start switch 180 also closes to activate the timing circuit 264 in the card reader 246 for generating a programmed lip heat time. As noted earlier, no heating power level information is fed to the induction heater power supply 376 in this step. The latter power supply is preset to energize the crucible heating coil 23 at a minimum power level under these conditions. This power level is selected to effect preheating of the crucible lip and cooling of the molten metal to a temperature slightly above the programmed metal pouring temperature during the programmed lip heat delay time. At the expiration of the lip heat delay, the timing circuit applies a stepping voltage to the program sequencer 42 through its currently closed time delay step switch 138. The sequencer then advances to its 11th stepping position.

In the 10th stepping position of the sequencer 42, its pour temperature select switch 182 closes to feed a programmed pour temperature signal from the card reader 246 to the temperature monitor 52. Accordingly, the wiper arm 366b of the monitor output signal generator 366 assumes a position related to the temperature error between the molten metal temperature and the programmed pour temperature. In the 11th stepping position, the sequencer power lock switch 154 recloses to lock the wiper arm in its current position and connect the arm to the heat controller 48. The output power of the induction heater power supply 376 in the heat controller is then adjusted to a level proportional to the temperature error. Closure of the sequencer power lock switch 154 also energizes the fixed delay timer 158 to commence running of its fixed heating delay time, i.e. 1 minute. At the expiration of this delay, the timer contacts 158a reclose to step the program sequencer 42 to its 12th stepping position. In the 11th stepping position, the lip heat angle select switch 178 reopens so that no angle select signal is fed to the crucible drive controller 45. This controller then energizes the crucible drive

motor 25 to rotate the crucible 22 at the creep rate to its upright metal temperature reading position, as noted earlier.

Program sequencer 42, in its 12th stepping position, closes its temperature interrogate switch 196 to energize the fixed delay timer 198. This timer generates a short delay time to permit thermal stabilization of the temperature monitor 52. At the expiration of this delay, the timer contacts 198a close to apply a temperature interrogate signal to the movable limit switch contact 372a in the temperature monitor. If the current position of the wiper arm 366b of the monitor output signal generator 366 is above, i.e. at the cold side, of the hold power tap H of its resistor 366a, indicating that the metal temperature is below the programmed pour temperature, a stepping voltage is applied to the sequencer backstepping lead 70 through the monitor limit switch contact 372b. The program sequencer 42 is then returned to its 11th step to repeat the latter step at a heating power level proportional to the temperature error between the programmed pour temperature and the current metal temperature. On the other hand, if the current position of the wiper arm 366b is below, i.e. at the hot side, of the hold power tap H, indicating that the metal temperature exceeds the programmed pour temperature, the movable limit switch contact 372a in the temperature monitor 52 will be closed to its contact 372c and limit switch 374 will be open so that no stepping voltage is applied to the program sequencer. waits, these conditions, the system units, applying heating power to the crucible heating coil 23 at the preset low level, until the metal cools to the exact level of the programmed pour temperature. Limit switch 374 then closes to apply a stepping voltage to the sequencer forward stepping lead 68 and thereby advance the sequencer to its 13th stepping position.

At this point, it is significant to recall that in the 12th stepping position, the crucible 22 occupies its upright position wherein the temperature sensor 30 can accurately respond to the metal temperature. Also, no power level signal is applied to the heat controller 48 so that the latter energizes the crucible heating coil 23 at a preset low level, as noted earlier, which permits cooling of the metal to the programmed pouring temperature, as stated.

In the 13th stepping position of the program sequencer 42, its hold power select switch 160 recloses to resume heating of the metal in the crucible 22 at the programmed hold power level. The sequencer pour angle select 204 closes to feed a programmed pour angle signal to the crucible drive controller 45. However, since the sequencer creep relay switch 74 is now open to deenergize the drive controller creep relay 308 and both controller pour speed relays 310 and 312 are also currently deenergized, the crucible 22 remains in its upright position. Stepping of the sequencer 42 to its 13th stepping position also closes its vacuum stepping switch 208 to verify the vacuum level in the vacuum chamber 12. If the chamber vacuum level at least equals the programmed pour vacuum level, the vacuum level detector 16 applies a stepping voltage to the sequencer forward stepping lead 68 through the card reader 246 and the sequencer switch 208 to advance the sequencer 42 to its 14th stepping position.

In the 14th stepping position of the sequencer 42, its pour switch 220 closes to energize the solenoid 416 of the mold lid position controller valve 400. The valve then shifts to its position of FIG. 12 to raise the mold lid 26. Arrival of the lid at its raised position closes the mold lid operator limit switch 224 to feed a programmed pour speed signal from the card reader 246 to the crucible drive controller 45. This signal energizes the corresponding pour relay 310 or 312 within the controller to cause rotation of the crucible 22 to its programmed pour angle at the programmed pour speed. The molten metal is thereby poured from the crucible into the mold 18. As noted earlier, the pour speed is selected and the pivot axis of the mold is located to cause entrance of the molten stream into the mold without contact with the mold rim throughout the pouring cycle. During rotation of the crucible 22 to its final programmed pouring angle, the 80° contacts 121 reclose to

restart the fixed delay timer 122. At the expiration of the fixed time delay generated by this timer which is selected to slightly exceed the maximum pouring time, the timer contacts 122a reclose to apply a stepping voltage to the sequencer 42 through its currently closed 80° stepping switch 116. The sequencer then advances to its 15th stepping position.

In the 15th stepping position, the sequencer load angle select switch 72 and creep relay switch 74 reclose to cause return of the crucible 22 at the creep rate to its load angle position. The sequencer heat start switch 130 reopens to cut heating power to the crucible heating coil 23. The sequencer vent delay switch 228 closes to actuate the card reader timing circuit for generating the programmed vent time delay which is selected to permit cooling of the metal in the mold 18 under vacuum. At the expiration of this vent time delay, the timing circuit applies a stepping voltage to the sequencer 42 through its currently closed time delay stepping switch 138. The sequencer is then returned to its home position to complete the casting cycle. This final stepping of the sequencer reopens the heat-vacuum controller or switch 110 to cut power to the vacuum and heat controllers 46, 48. The vacuum pump valve 328 is thereby deenergized to vent the vacuum chamber to atmosphere.

At this point, it is significant to recall that the described casting cycle is illustrative only and may be varied by adjusting the sequencer 42, as by changing the positions of its switch-operating pins 63, to vary the sequence of the casting steps and/or by eliminating or adding additional steps.

As noted earlier, the casting apparatus includes a manual programmer 40. Referring to FIGS. 6 and 13, the manual programmer includes a pour speed selector switch 500 having a movable contact 500a and two fixed contacts 500b and 500c. Movable contact 500a is energized from the DC source 36a through the lead 257 of the cable 258. The fixed selector contacts 500b, 500c are connected to card reader pour speed terminals 282A-S, 282A-F through leads of a cable 502 having a plug 504 which is insertable into a receptacle 506 on the card reader 246 and leads of a cable 508 within the reader. Thus, the selector switch 500 may be set to energize either pour speed terminal of the reader.

Also included in the manual programmer 40 are a heat start vacuum selector switch 510 and a pour vacuum selector switch 512. These switches have fixed contacts 510a, 512a connected to the pressure transducer leads 128a, respectively, of the cable 128 from the vacuum level detector 16. The switches have movable contacts 510b, 512b connected to the heat start and pour vacuum level terminals 282B, 282C, respectively, of the card reader through leads of the cables 502, 508. From this description, it will be understood that the selector switches 510, 512 may be set to selectively connect the vacuum level detector pressure transducers 259 to the vacuum level terminals of the card reader.

A series of angle, heating power level, and temperature select variable voltage dividers 514 are included in the manual programmer. These voltage dividers have resistors 514a energized from the regulated DC voltage source 36b through lead 263 of the cable 258. The movable contacts 514b of the voltage dividers are connected to the angle, heating power level, and temperature terminals 282D through 282L, respectively, of the card reader through the cables 502, 508. The latter terminals may thus be energized at selected voltage levels by adjustment of the voltage dividers.

The manual programmer includes three adjustable timers 516, 518, and 520 for generatively selectively variable melt, lip heat, and vent time delays, respectively. The timing means of these timers are energized from the AC source 36c through lead 279 of cable 258. The timing start terminals of the timers are connected through leads of the cables 502, 508 to the card reader time delay start terminals 282M, 282N, 282P. The timer outputs are connected through a common lead of the latter cables to the card reader time delay stepping terminal 282Q. Each timer 516, 518, and 520 is activated to generate a time delay determined by its circuit setting in response to

energizing of the corresponding card reader time delay start terminal 282M, 282N, or 282P. At the expiration of this delay, the timer produces a stepping voltage at the card reader time delay stepping terminal 282Q.

5 The manual programmer 40 is used by inserting a blank program card 240, i.e., a card having no holes, into the card reader 246 for isolating the reader base and cover contacts 250, 254 and inserting the programmer plug 504 into the reader receptacle 506. The manual programmer may then be 10 adjusted to establish any desired casting program after which the casting cycle of the apparatus may be initiated, as before. This cycle will proceed in accordance with the manually set program. Thus, the manual programmer may be utilized to try out various casting programs to determine the optimum program for a given application. This optimum program can then be established on a program card 240 for controlling the casting cycle as described earlier. The manual programmer is disconnected from the card reader by removing the plug 504 15 from the receptacle 506 when using the program card.

What is claimed as new in support of letters patent is:

1. Automatic casting apparatus comprising:
a crucible for containing a metal to be cast;
a motor for driving said crucible through a range of angular

positions;
an induction heater for heating said metal to the molten state;

means for sensing and generating a signal related to the angular position of said crucible;

means for sensing and generating a signal representing the temperature of the molten metal in said crucible;

programmer means including means for storing information providing a casting program representing preselected program parameters including melt and pour angles for said crucible, a heating power level for said heater, and a metal pouring temperature and selectively actuatable means for reading said parameters in sequence in response to successive actuations of said programmer means and producing a signal representing each parameter; and

automatic control means including means for operating said motor and heater in response to said signals and means for actuating said programmer means to advance said program from one parameter to the next at the completion of each operation in response to a parameter signal to cause said apparatus to proceed through an automatic casting cycle involving initial operation of said motor in response to the melt angle signal to drive said crucible to said melt angle, operation of said heater in response to the heating power level signal to heat said metal to the molten state at said heating power level while said crucible occupies said melt angle and to thereafter heat the molten metal to said pouring temperature in response to the pouring temperature signal, and operation of said motor in response to the pour angle signal following heating of the molten metal to said pouring temperature to rotate said crucible to said pour angle.

2. Automatic casting apparatus according to claim 1, wherein:

said program parameters include a parameter representing a rate of rotation of said crucible to said pour angle;
said programmer means produces a tilt rate signal representing said rotation rate;

means for sensing and generating a signal representing the rotational speed of said crucible; and

said control means operates said motor in response to said signals to cause rotation of said crucible to said pour angle at said rotation rate.

3. Automatic casting apparatus according to claim 1, wherein:

said crucible has a pouring lip;

said program parameters include a parameter representing a lip heat angle for said crucible wherein the molten metal within the crucible contacts but does not overflow said

pouring lip and a parameter representing a lip heat delay time;
said programmer means produces a signal representing said lip heat angle and a signal representing said lip heat delay time; and
said control means operates said motor in response to said signals to rotate said crucible to and retain the crucible at said lip heat angle for said lip heat delay time following heating of said metal to the molten state and prior to rotation of said crucible to said pour angle, thereby to heat said lip prior to pouring of the molten metal.

4. Automatic casting apparatus according to claim 3, wherein:

said program parameters include a parameter representing a superheat temperature in excess of said pouring temperature; 15
said programmer means produces a signal representing said superheat temperature; and
said control means operates said heater in response to said signals to heat said metal to the molten state and then heat the molten metal to said superheat temperature while said crucible occupies said melt angle and to thereafter bring the temperature of the molten metal to said pouring temperature following heating of said crucible pouring lip.

5. Automatic casting apparatus according to claim 3, wherein:

said control means includes means for operating said heater at a reduced heating power level during heating of said pouring lip; and
said superheat temperature, lip heat delay time, and reduced power level are selected to effect heating of said pouring lip to a given lip temperature and concurrent cooling of said molten metal approximately to said pouring temperature.

6. Automatic casting apparatus according to claim 1, wherein:

said program parameters include a parameter representing an initial temperature of said molten metal and a parameter representing a heating delay time at said heating power level required to heat the molten metal to a selected temperature less than said initial temperature; 40
said programmer means produces a signal representing said initial temperature and a signal representing said heating delay time; and
said control means includes means for operating said heater in response to said power level signal to initially heat said metal at said heating power level for said heating delay time, heating said metal for an additional fixed delay time, and then alternately comparing the temperature of said molten metal to said initial temperature and heating said metal for said fixed delay time at a power level related to the temperature error between the metal temperature and said initial temperature until the temperature of the molten metal approximately equals said initial temperature, all prior to rotation of said crucible to said pour angle.

7. Automatic casting apparatus according to claim 6, wherein:

said crucible has a pouring lip;
said program parameters include a parameter representing a lip heat angle of said crucible wherein the molten metal within the crucible contacts but does not overflow said pouring lip and a parameter representing a lip heat delay time; 65
said programmer means produces a signal representing said lip heat angle and a signal representing said lip heat delay time;
said control means includes means for operating said heater at a reduced heating power level during heating of said pouring lip;
said control means operates said motor in response to said signals to rotate said crucible to and retain the crucible at

said lip heat angle for said lip heat delay time following heating of said metal to the molten state and prior to rotation of said crucible to said pour angle, thereby to heat said lip prior to pouring of the molten metal;

said initial temperature is a superheat temperature in excess of said pouring temperature; and

said superheat temperature, lip heat delay time, and reduced power level are selected to effect heating of said pouring lip to a given lip temperature and concurrent cooling of said molten metal approximately to said pouring temperature.

8. Automatic casting apparatus according to claim 7, wherein:

said control means includes means for comparing the temperature of the molten metal to said pouring temperature and operating said heater to bring said molten metal to said pouring temperature after expiration of said lip heat delay.

9. Automatic casting apparatus according to claim 8, wherein:

said program parameters include a parameter representing a rate of rotation of said crucible to said pouring angle; said programmer means produces a signal representing said rotation rate;

means for sensing and generating a signal representing the rotational speed of said crucible; and
said control means operates said motor in response to said signals to rotate said crucible from said upright position to said pour angle at said rotation rate.

10. Automatic casting apparatus comprising:

a vacuum chamber;
vacuum pumping means for evacuating said chamber;
a vacuum level detector for producing signals related to the vacuum level within said chamber;
a crucible within said chamber for containing a metal to be cast;

a motor for driving said crucible through a range of angular positions;

means for sensing and generating a signal representing the angular position of said crucible;

an induction heater for heating said metal to the molten state;

means for sensing and generating a signal representing the temperature of the molten metal in said crucible;

programmer means including means for storing information providing a casting program representing preselected program parameters including a heat start vacuum level for said chamber, melt and pour angles for said crucible, a heating power level for said heater, and a metal pouring temperature, and selectively actuatable means for reading said parameters in sequence in response to successive actuations of said programmer means and producing a signal representing each parameter; and

control means including means for operating said motor and heater in response to said signals and means for actuating said programmer means to advance said program from one parameter to the next at the completion of each operation in response to a parameter signal to cause said apparatus to proceed through an automatic casting cycle involving initial operation of said pumping means to evacuate said chamber, operation of said motor in response to the melt angle signal to drive said crucible to said melt angle, operation of said heater in response to the heating power level signal to heat said metal to the molten state at said heating power level while said crucible occupies said melt angle and thereafter heat the molten metal to said pouring temperature in response to the pouring temperature signal, and operation of said motor in response to the pour angle signal following heating of the molten metal to said pouring temperature to rotate said crucible to said pour angle.

11. Automatic casting apparatus according to claim 10, wherein:

said program parameters include a parameter representing a pour vacuum level for said chamber; said programmer means produces a signal representing said pour vacuum level; and

said control means operates said motor in response to said signals to rotate said crucible to said pour angle following heating of said metal to said pour temperature and reduction of the chamber pressure to said pour vacuum level.

12. Automatic casting apparatus according to claim 10, wherein:

said program parameters include a parameter representing a rate of rotation of said crucible to said pour angle; said programmer means produces a signal representing said rotation rate;

means for sensing and generating a signal representing the rotational speed of said crucible; and

said control means operates said motor in response to said signals to cause rotation of said crucible to said pour angle at said rotation rate.

13. Automatic casting apparatus according to claim 10, wherein:

said crucible has a pouring lip;

said program parameters include a parameter representing a lip heat angle for said crucible wherein the molten metal within the crucible contacts but does not overflow said pouring lip and a parameter representing a lip heat delay time;

said programmer means produces a signal representing said lip heat angle and a signal representing said lip heat delay time; and

said control means operates said motor in response to said signals to rotate said crucible to and retain the crucible at said lip heat angle for said lip heat delay time following heating of said metal to the molten state and prior to rotation of said crucible to said pour angle, thereby to heat said lip prior to pouring of the molten metal.

14. Automatic casting apparatus according to claim 13, wherein:

said program parameters include a parameter representing a superheat temperature in excess of said pouring temperature;

said programmer means produces a signal representing said superheat temperature; and

said control means operates said heater in response to said signals to heat said metal to the molten state and then heat the molten metal to said superheat temperature while said crucible occupies said melt angle and to thereafter bring the temperature of the molten metal to said pouring temperature following heating of said crucible pouring lip.

15. Automatic casting apparatus according to claim 14, wherein:

said control means includes means for operating said heater to heat said molten metal at a reduced heating power level during heating of said pouring lip; and

said superheat temperature, lip heat delay time, and reduced power level are selected to effect heating of said pouring lip to a given lip temperature and concurrent cooling of said molten metal approximately to said pouring temperature.

16. Automatic casting apparatus according to claim 10, wherein:

said program parameters include a parameter representing an initial temperature of said molten metal and a parameter representing a heating delay time at said heating power level required to heat the molten metal to a selected temperature less than said initial temperature;

said programmer means produces a signal representing said initial temperature and a signal related to said heating delay time; and

said control means includes means for operating said heater in response to said signals to initially heat said metal at said heating power level for said heating delay time, heat-

ing said metal for an additional fixed delay time, and then alternately comparing the temperature of said molten metal to said initial temperature and heating said metal for said fixed delay time at a power level related to the temperature error between the metal temperature and said initial temperature until the temperature of the molten metal approximately equals said initial temperature, all prior to rotation of said crucible to said pour angle.

17. Automatic casting apparatus according to claim 16, wherein:

said crucible has a pouring lip;

said program parameters include a parameter representing a lip heat angle of said crucible wherein the crucible contacts but does not overflow said pouring lip and a parameter representing a lip heat delay time;

said programmer means produces a signal representing said lip heat angle and a signal representing said lip heat delay time;

said control means operates said motor in response to said signals to rotate said crucible to and retain the crucible at said lip heat angle for said lip heat delay time following heating of said metal to the molten state and prior to rotation of said crucible to said pour angle, thereby to heat said lip prior to pouring of the molten metal;

said initial temperature is a superheat temperature in excess of said pouring temperature; and

said superheat temperature, lip heat delay time, and reduced power level are selected to effect heating of said pouring lip to a given lip temperature and concurrent cooling of said molten metal approximately to said pouring temperature.

18. Automatic casting apparatus according to claim 17, wherein:

said control means includes means for comparing the temperature of the molten metal to said pouring temperature, and operating said heater to bring said molten metal to said pouring temperature after expiration of said lip heat delay.

19. Automatic casting apparatus according to claim 10, wherein:

said program parameters include a parameter representing a rate of rotation of said crucible to said pouring angle;

said programmer means produces a signal related to said rotation rate;

means for sensing and generating a signal representing the rotational speed of said crucible; and

said control means operates said motor in response to said signals to rotate said crucible to said pour angle at said rotation rate.

20. Automatic casting apparatus comprising:

a crucible for containing a metal to be cast;

a motor for driving said crucible through a range of angular positions;

an induction heater for heating said metal to the molten state;

means for sensing and generating a signal related to the angular position of said crucible;

means for sensing and producing a signal representing the temperature of the molten metal in said crucible;

programmer means including means for storing information providing a casting program representing preselected program parameters including melt and pour angles of said crucible, a heating power level for said heater, and a metal pouring temperature, and selectively actuatable means for reading said parameters in sequence in response to successive actuations of said programmer means and producing a signal representing each parameter;

a crucible drive controller responsive to said crucible angle signals and connected to said motor for operating said motor to rotate said crucible to said melt and pour angles in response to said melt and pour angle signals;

a temperature monitor 39 connected to said thermal sensor and responsive to said pour temperature and metal temperature signals for generating a controlled power level signal related to the error between said pour and metal temperatures;

a heat controller responsive to aid heating power level and controlled power level signals and connected to said heater for operating said heater at said heating power level in response to said heating power level signal and at a heat power level related to said temperature error in 10 response to said controlled power level signal;

means for applying said angle signals to said drive controller and said heating power level and controlled power level signals to said heat controller to produce a casting cycle having successive steps involving operation of said motor 15

5
40
 to drive said crucible to said melt angle, operation of said heater following rotation of said crucible to said melt angle to heat said metal to the molten state at said heating power level while said crucible occupies said melt angle and to thereafter heat the molten metal to said pouring temperature, and operation of said motor following heating of the molten metal to said pouring temperature to rotate said crucible to said pour angle; and
 means for actuating said programmer means to advance said program from one parameter to the next at the completion of each operation in response to a parameter signal to cause said apparatus to proceed through said casting cycle.
